UNITED STATES PATENT OFFICE.

JOHN P. WEIS, OF NYACK, NEW YORK.

SEWING MACHINE.

Application filed June 28, 1921. Serial No. 431,032.

To all whom it may concern:

Be it known that I, JOHN P. WEIS, a citizen of the United States, residing at Nyack, in the county of Rockland and State of New York, have invented certain new and useful Improvements in Sewing Machines, of which the following is a specification.

This invention relates to sewing machines of the type or style having a cylindrical bed or horn wherein the feeding and part of the stitching mechanisms are contained and operated for the purpose of operating upon or forming tubular goods, an object thereof being to provide an improved machine which can be operated at very high speeds, stopping and starting instantly, or as rapidly or slowly as desired without undue noise, shock, or vibration, the construction being such as to require a minimum amount of care, adjustment, replacement, and oiling. In the present machine the parts are automatically lubricated and the presser foot is also automatically operated so that the operator need only guide the work and manipulate the treadle to control the machine, thereby avoiding the loss of time resulting from the continuous stopping and turning of the hand wheel during the operation of the machine in order to bring the needles to rest in their highest position and raise the presser foot to position the work.

The present invention is an improvement over my Patent 1,221,254, dated April 3, 1917, and comprises as a unitary structure the combination of stitching mechanism, feeding mechanism, needle thread controlling mechanism, speed regulating mechanism, starting and stopping mechanism, and lubricating mechanism, the machine being adapted to perform or carry out a wide variety of stitching operations as well as different kinds of stitch formation, needle gauges, etc.

Other objects of this invention will appear in the following description thereof, reference being had to the accompanying drawings forming a part of the specification, wherein like reference characters indicate corresponding parts in the several views and wherein Fig. 1 is a side elevation of the machine with the end cap or cover of the looper mechanism shown in dotted lines, and the transmitter shown in operating position under the machine, but detached from the work table to more clearly illustrate the relation of the transmitter with the sewing

machine; Fig. 2 is a top plan view of the transmitter shown in Fig. 1; Fig. 3 is a front perspective view of the sewing machine, transmitter and treadle connected for operating the same; Fig. 4 is a perspective view of the hand wheel and its shaft having clutch teeth in the end for turning the mechanism of the machine by hand; Fig. 5 is a perspective view of the end cap for covering the looper and thread controlling mechanisms; Fig. 6 is an end view of the needle bar operating mechanism, portions of the needle bar bushings, oil cup, and needle bar broken away to clearly show the construction, and a portion of the arm and crank shaft shown in broken lines; Fig. 7 is a perspective view showing the inside wall of the back cover plate with the stop motion lever and its connecting parts assembled thereto; Fig. 8 is a back elevation of the machine, illustrating the connections for the needle drive and a portion of the looper and feed actuating mechanisms; Fig. 9 is a detail view of the collar which forms a retainer for the clutch spring; Fig. 10 is a fragmentary perspective view of a portion of the crank shaft and stop clutch shaft; Fig. 10^a is a transverse section taken substantially on line 10^a of Fig. 10, and shows particularly the stop clutch balls in a clutched position; Fig. 11^a is a view similar to Fig. 10^a, but shows the stop clutch balls in a non-clutching position; Fig. 11 is a vertical section taken through the vertical center line of the crank shaft bearing, showing the crank shaft, the assemblage of the clutch wheel with a portion of the stop motion mechanism, and the clutch hand wheel for turning the mechanism of the machine by hand, the frame of the machine being represented by broken lines; Fig. 12 is a top plan view of the feeding mechanism, the overhanging arm and cylinder of the machine being shown in broken lines; Fig. 13 is a sectional view taken on lines 13-13 of Fig. 15 of the feed and adjusting means for changing the length of the stitch; Fig. 14 is a sectional detail view-taken on lines 14-14 of Fig. 15--of a portion of the feed bar showing the eccentric bushing, lock nut and screw which comprises means for raising and lowering the feed; Fig. 15 is a side elevation of the feeding mechanism, parts being broken away to clearly show the assemblage, the overhanging portion of the arm and the machine frame being indicated.

in broken lines; Fig. 16 is a top plan view of the cylindrical portion of the machine illustrating the looper mechanism; Fig. 17 is a side elevation of the mechanism shown in Fig. 16, the overhanging arm of the machine being indicated in broken lines; Fig. 18 is an end elevation of the cylinder, illustrating the mounting of the loopers and needle guards; Fig. 19 is a perspective view of the circular holder for the loopers; Fig. 20 is a perspective view of the arm which supports the circular holder for the loopers; Fig. 21 is a perspective view of the looper; Fig. 22 is a perspective view of the needle guard and holder therefor; Fig. 23 is a detail view of the lower end of the looper actuating connections, a portion being broken away to clearly show the assemblage of the parts; Fig. 24 is an end elevation of the cylinder and looper actuating means, partly in section taken on lines 24—24 of Fig. 16; Fig. 25 illustrates diagrammatically the movement of the looper actuating means; Fig. 26 illustrates diagrammatically the elliptical path of movement of the loopers; Fig. 27 is a diagrammatic view illustrating the manner in which adjustment of the looper mechanism may be made in order to change the oscillation of the loopers from front to rear of the needles, for cooperation of the loopers with needles of different sizes; Fig. 28 is an end view of the cylinder showing the looper thread controlling means, with the looper in its extreme forward position; Fig. 29 is a perspective view of a group of parts of the looper thread controlling means; Fig. 30 is a view of the parts shown in Fig. 28 with the looper in position for the needle to enter between it and a strand of the looper thread, also showing the thread clamped by the thread controlling mechanism in full and dotted line position, the full lines representing the thread being clamped while the needle is moving downward and the looper is moving backward, and the dotted line position representing the thread clamp open, for free movement of the looper thread while the looper is moving in the opposite direction; Fig. 31 is a fragmentary perspective view of the end of the cylinder, showing a portion of the throat plate, looper thread clamping means, and the looper thread guide tubes which conduct the thread from the rear of the machine to the thread controlling mechanism; Fig. 32 is a view similar to Figs. 30 and 28 but showing the looper in its rearmost position, where it shifts from front to rear of the needles, and at which time the thread clamp is open as the needle starts to rise and the looper moves toward it to enter the needle loop; Fig. 33 is a perspective view of the looper thread take-up or controller; Fig. 34 is a detail elevation view of the looper thread guide tubes,

thread clamp, and a portion of the rock lever with guide eyes for conducting the thread to the loopers; Fig. 35 is a side elevation showing the overhanging arm of the machine in broken lines, the presser foot and lifting mechanism therefor, also the needle thread controlling mechanism in dotted line and full line positions; Fig. 36 is a detail view showing the portion of the presser foot lifting lever with a latch hook attached thereto adapted to hold the presser foot in lifted position when swung to the dotted line position of the figure; Fig. 37 is a detail plan view of the stop lever, showing its mounting in the cover plate and machine frame, the same being shown in broken lines; Fig. 38 is a side elevation of the stop lever shown in Figs. 7 and 37, the actuating rod therefor, the stop clutch brake shoe and brake shoe lever being shown in full lines, and the frame in broken lines; Fig. 39 is a sectional detail view of the actuating rod for the stop mechanism, taken on lines 39—39 of Fig. 38; Fig. 40 is a vertical sectional view of the crank shaft and bearings thereof illustrating the manner in which the parts are lubricated from the overhead reservoir and the tubular outlets leading to the several bearings, also showing in elevation the oil pump, the oil pump drive wheel, and the tubes conducting the oil from the oil pump to the reservoir at the top of the machine; Fig. 41 is a side elevation of the mechanism shown in Fig. 40, illustrating the drip lip attached to the inside inclined face of the rear cover for conducting a portion of the lubricant to the shock absorbing oil buffer carried by the stop lever; Fig. 42 is a detail view of the reservoir at the top of the machine, portions broken away to show the filter and the construction of the oil gauge or indicator; Fig. 43 is a sectional view of the rotary top stitch forming mechanism, the machine frame and cylinder being indicated in broken lines; Fig. 44 is an end view of the mechanism illustrated in Fig. 43, the crank shaft and the frame of the machine being indicated in broken lines; Fig. 45 is a sectional view of the presser foot and stitch mechanism carried thereby, taken on the lines 45—45 of Fig. 43 looking in the direction of the arrow; Fig. 46 is a sectional view of the presser foot and stitch forming mechanism carried thereby, taken on the lines 46—46 of Fig. 44; Fig. 47 is a side elevation partly in section of the needle vibrating mechanism for making zig-zag stitches, the needle bar being shown as pivotally mounted in the head of the machine for swinging, angular, and reciprocatory movement, the frame and cylinder being indicated in broken lines; Fig. 48 is an end view of the mechanism shown in Fig. 47, the crank shaft and frame of the machine be-

ing indicated in broken lines; and Fig. 49 is an end view of the mechanism for imparting zig-zag movements to the needle bar at right angles to its line of vertical reciprocation.

The machine frame.

Referring particularly to Figures 1, 3, 6, 8, 11, 38, 40, and 41, it will be seen that the present machine is mounted on a suitable table 1 and comprises a machine frame of special construction having flanges 2 and 3 for supporting and securing the machine to the table. The main or upright trunk portion of the frame is preferably of hollow rectangular construction, closed at the bottom and having a front wall 4, and a rear wall 5 provided with an opening 6 adapted to be closed by a cover plate 7 attached thereto in any suitable manner. This cover plate has a hollow projection 8 within which operates a stop lever 118. The outline or shape of the opening 6 is irregular in form and is indicated at 6^a, 6^b, 6^c, 6^d, 6^e, and 6^f, Figure 8, the cover plate 7 being of similar form and adapted when closed to seal the opening against leakage of oil.

As shown in Figures 28 and 41 the rear wall 5 is inclined to the left of the perpendicular, an advantage thereof being to assist in properly conducting the lubricant from one interior part to another and to finally conduct it into the reservoir formed by the bottom 9 and side walls 4, 5, 13, and 16 of the frame. To empty the reservoir I provide a drain pipe 10 tapped into the bottom 9. The front wall 4 is provided with a boss 11, bored to receive the cylinder 12. The side wall 13 is provided with a boss 14 to receive one of the crank shaft bushings 15. The opposite side wall 16 has a projecting rib 17 parallel to the wall 4, curved at 18, and provided with two bosses 19, the rib extending down the opposite side, parallel to the rear wall 5 as at 20, Figure 38.

Located on the side wall 16 near the bottom is a boss 21, forming together with the bosses 19 a suitable seat for the belt guard 22 which covers the drive belt 23, and the clutch and pump wheels 93 and 425.

The side wall 16 has a rectangular opening 24 into which projects the laterally extending portion 118^a of the stop lever, Figure 37, this opening also affording a passage for the lubricant returning from the outer bearing 25 of the bushing 99 carried by the belt guard 22, Figures 8 and 11. Above the opening 24 in the side wall 16 is an inwardly projecting boss 26 bored to receive bushings 101 and 101^a for supporting the crank shaft. The top portion of the frame carrying the boss 26 is indicated at 27 and the top wall of the frame at 28, Figure 40, wherein the needle driving means

and oil distributing reservoir is located. Projecting inwardly from the front wall is a boss 29 also bored to receive a bushing 29^a for supporting the crank shaft. Adjacent to the bottom 9 of the frame, and located in the side wall 16 is an inwardly projecting boss 30 bored to receive a pump casting 31.

Projecting from the front wall 4 is an overhanging arm 32 terminating in the needle bar and presser bar bearings 33, having outer walls 35 and 36. Above these bearings is a rectangular opening 34 through which the pressed spring and lifter lever operate. This overhanging arm 32 is provided with suitable bearings 37 and 38 for the needle operating rock shaft 39. Secured to the forward end of the rock shaft 39 by screws 40 is a needle bar operating arm 41. The end of the shaft 39 is tapped to receive a screw 42 and a thrust washer 43 thereby to prevent end movement of the arm 41 on the shaft 39. At the outer end of the arm 41 by means of a joint pin 44 is secured a link 45, the bottom end thereof being connected by means of a joint pin 46 to an end piece 47 tapped into the needle bar 48 and clamped with a lock nut 49. The needle bar is hollow and the lower end is tapped to receive the needle holder 50 which carries the needles 51. The needle bar is provided with two openings 52, the upper one being an inlet and the lower one an outlet for oil for the purpose of internally oiling the upper and lower needle bar bushings, 53 and 54.

Secured to the top of the upper bushing 54 is an oil cup 55 provided with a felt oiler, carrying sufficient lubricant for the needle bar, but preventing the oil from dripping and soiling the goods. An intermediate felt oiler 56 is provided between the two bushings. These felt oilers wipe the needle bar in its reciprocating movement, keeping it clean and properly lubricated.

To the rear end of the rock shaft 39, adjacent to the bearing 37 is secured a crank arm 57 and ball stud 58, to which is connected the upper end of a ball connection 59. The lower end 60 also has a ball socket to fit over the ball 61 of the crank shaft.

The rotary drive or crank shaft and its clutch mechanisms.

With reference particularly to Figures 8, 9, 10, 11, and 40, the crank shaft comprises bearing portions 62 and 63, the bearing 62 being integral with the crank disc 64 and the ball 61. The crank 65 is integral with the ball 61 and the portion of the shaft 63, the crank 66 is also integral with the shaft portion 63 and with a ball 67, and the crank disc 68 is integral with balls 67 and 69, the latter forming a part of the shaft portion 70, shown in section in Fig. 11. The end

120

125

130

portion 62 of the crank shaft is provided with a series of clutch teeth 72 to co-act with other clutch teeth 73 carried by a stub shaft 74 secured to a hand wheel 75 adapted for the purpose of turning the crank shaft and operating the mechanism of the machine by hand, if desired. The shaft 74 is provided with a reduced neck 76 for the reception of the coiled spring 77 carried in the annular groove 78 of the bushing 15. The position of the spring with respect to the shaft neck 76 is such as to normally hold the clutch teeth 73 out of engagement with the clutch teeth 72, the contraction of the spring 77 on the edge 79 of the neck tending to draw the shaft outward. Thus when the hand wheel 75 is forced inward by the hand of the operator to engage the clutch teeth for turning the shaft, the spring 77 is forced out of the neck and is expanded so as to cause the same to embrace the edge 79. When the inward pressure of the hand upon the wheel is removed, the contraction of the spring draws the shaft to a position where the spring enters the neck 76, disengaging the clutch teeth, and thus preventing the wheel from rotating during the operation of the machine.

From the foregoing it will be understood that I have provided a means, in the form of a hand clutch wheel whereby the mechanism of the machine may be readily turned by hand, such means being easily detachable from the machine by withdrawing the same as illustrated in Figure 4. This feature is of considerable importance as it avoids the rotating of the hand wheel each time the machine is started, thus saving considerable power, and obviating the necessity of stopping the wheel since the same in the present machine is disconnected from the shaft at the time of starting and stopping and during the operation of the machine. In order to quickly start and stop a mechanism that is operated at a high speed such as three or four thousand revolutions per minute, all unnecessary weight and bulk of rotary parts must be eliminated. An important advantage of this improved machine resides in the elimination of the weight of the usual hand wheel in operation and the centrifugal force set up thereby, whereas if the wheel were directly connected to the shaft it would be very difficult, if not impossible, to bring the parts operating at such high speeds to a dead stop instantly, without excessive wear and tear on the mechanism.

The usual sewing machine is provided with a hand wheel which is grasped by the hand of the operator at the end of each stitching operation. The wheel is then turned to raise the needle to a position of rest to permit the removal of the work. This continuous stopping and turning of the

hand wheel during the rapid operation of the machine becomes a laborious task, as it must often be repeated thousands of times daily, thereby consuming a considerable part of the operator's time. In many instances 70 ten to twenty per cent of the time consumed in stitching operations is spent in manipulating the hand wheel. In the present machine this stopping of the machine and turning of the wheel by hand to bring the needle at rest in its highest position is obviated by virtue of the provision of a positive stop motion, in the present instance the same embodying certain improvements over my Patent No. 1,352,333, dated September 7, 1920. 80 A detailed description of these stop motion parts is deemed unnecessary since the same are fully described in the aforesaid patent.

Referring particularly to Figures 7, 8, 9, 10, 11, 37, and 38, it will be seen that the 85 portion of the shaft 70 is drilled at 80 to receive the reduced end 71 of the stop clutch shaft. A portion of the shaft extension 70 is enlarged to form the semi-circular keyway 81 which extends the entire length of 90 the hole 80 and receives a semi-circular key 82 formed as an integral part of the reduced portion 71 of the stop clutch shaft. The telescoping of these parts provides a convenient way of connecting the parts for quick 95 coupling and uncoupling, as it is necessary at times to withdraw the stop clutch shaft in order to renew the wedge blocks 83 herein-after described or other parts.

Adjacent to the end portion 70 of the 100 crank shaft, and between the faces of the bushings 101^a and 101, is located a collar 86 provided with a hole 87^a, and a key way 87^b, adapted to receive and embrace the end 71 of the stop clutch shaft for rotary movement therewith. The bushing 101 is recessed to receive the collar 86 so that the faces of the two bushings are flush with each other, thereby limiting the movement of the collar. A coil spring 87 is carried in a groove 88 terminating at 87^c on one side of the center line of the shaft hole 87^a, see Figure 9, and on the other side terminating at 87^b. The groove has two openings 87^e and 87^f through the rear wall of the 110 collar 86, and through these openings the end of the spring 87 may be seen when assembling the parts, as one end of the spring abuts against the end 87^c while the other end exerts pressure against a pin 89 projecting through the opening 87^e and secured to and carried by a rockable stop clutch sleeve 90.

The stop clutch sleeve 90 is bored to fit 125 over the reduced end portion 71 of the stop clutch shaft and such bore is also provided with a semi-circular key-way to fit over the semi-circular key 82. The enlarged section 85 of the stop clutch shaft is provided with three radially disposed pockets 84 into which 130

are loosely seated segmental wedge blocks 83 which receive wedge balls 91. The sleeve 90 is bored to fit over the enlarged portion 85 of the stop clutch shaft, and such portion is 5 provided with three apertures, each of which carries a ball 91. The key-way of the sleeve being larger than the key permits the sleeve 90 to be rocked on the shaft by spring 87, as hereinafter described, sufficiently to cause 10 the three balls 91 to shift from a low non-clutching position on the wedge blocks 83 as illustrated in Fig. 11^a, to a clutching position where the balls are projected outwardly to grip the ball race 92 carried by the clutch 15 or driving wheel 93, as illustrated in Fig. 10^a. The clutch wheel 93 is provided with a belt groove 94, and is made in two sections having respectively hubs 95 and 96. The hub 95 operates in the bearing 97 while 20 the hub 96 operates in the bearing 98, so that the pull of the belt on the wheel 93 is taken up by these two bearings. The bearing 97 is formed in the bushing 99, carried by the boss 100 of the belt guard 22, and also forms 25 an end bearing for the enlarged end portion 85 of the stop clutch shaft. One end portion of the stop clutch sleeve 90 extends into the hubs 96 and 95 of the clutch wheel and the opposite end portion thereof has a bearing 30 in the bushing 101, supported in the boss 26 of the machine frame. This bearing is also in the form of a bushing and is provided with a cut-out 102 which extends up from the bottom for the entrance 35 of a stop finger. This cut-out registers with an eccentrically formed stop tooth 103 (see Fig. 38), formed in the clutch sleeve 90. Directly above the cut-out or opening 102 is located a brake shoe 104 which operates 40 in an opening 105 at the top of the bushing 101 against the stop clutch sleeve 90. A spring 106 is carried between a screw collar 108 and a shoulder 109 of a presser plug 107, and exerts downward pressure thereon, the shoulder 109 resting directly on the 45 brake shoe.

The stop and starting mechanisms and drive shaft brake mechanism.

50 The opposed surfaces of the presser plug and brake shoe are cut out forming a space between them to receive the free end 110 of the brake lifting lever 111 adapted to rock on a stud screw 112. The free end 55 of the brake lifting lever 111 is provided with a segmental or arcuate face 113 centered substantially at 114, Figure 38. Co-acting with the curved surface 113 is an anti-friction roller 115, secured by a shoulder screw 116, to an upstanding arm or projecting member 117 of a stop lever 118, mounted on conical screws 119 tapped into the side wall of the projecting portion 8 for 60 pivotally supporting the stop lever 118. A 65 stop finger 120 is connected by a joint pin

121 to the free end of the stop lever, the upper end 122 co-acting with the stop clutch tooth 103, and the lower end 123 co-acting with the oil buffer indicated generally at 70 124 which is supplied with oil from a reservoir 125, formed as a part of the stop lever.

To overcome the falling weight of the free end of the stop lever 118, a spring 126 attached at one end 127 to the inside wall of 75 the cover plate 7 is secured as at 128 to the stop lever, and normally urges the end 122 of the stop finger into engagement or co-action with the stop clutch tooth 103. From a consideration of Figs. 37 and 39 it 80 will be seen that the stop lever 118 is provided with a rectangular opening 129, within which is pivotally secured a sleeve 130 by screws 131 and 132. The reduced end 132^a of the screw 132 is somewhat longer than 85 the reduced end 131^a of the screw 131 so as to project through the wall of the sleeve and ride freely against the flattened face 133 of the push and pull rod 134, so that the end of the screw may engage the shoulder 90 135 of the flattened face 133 upon the predetermined downward travel of the rod. The top end 136 of the rod 134 co-acts with 95 a presser foot lifting mechanism, herein-after described.

The lower end of the rod 134 is connected as at 138 to an extension 137 passing through a guide aperture in the flange 3 and also through the work table 1, see Fig. 1, and is freely and slidably held in an elongated 100 slot 140 formed in the end of a lever 139 of the power transmitter by virtue of collars 141 and 142. Thus free up and down movement of the rod 137 in conjunction with lever 139 is obtained, the slot 140 permitting 105 the necessary play or lost motion between the parts.

*Operation of stop and starting mechanism.

The operation of these parts is as follows: The first downward movement of the starting rod 134 and 137 starts the driving belt 170 and the clutch wheel 93 begins to rotate. The stop lever carrying the stop finger is in such position that the end 122 110 is in contact with the clutch tooth 103; further downward movement of the rod brings the shoulder 135 in contact with the end 132^a of the screw in the lever and further downward movement of the rod will 115 then swing the stop lever on the pivots 119 bringing the stop finger 122 out of engagement with the clutch tooth 103. One-eighth of an inch movement of the finger is all 120 that is required to bring it out of engagement with the clutch; instantly as the finger clears the clutch the roller 115 engages the 125 brake lever 111 at 115^a which releases the pressure from the brake mechanism acting upon the clutch sleeve; as this pressure is 130

relieved the clutch is engaged and the crank shaft of the machine is coupled with the drive wheel 93 for rotary motion. Further downward movement of the starting rod increases the speed at which the machine may be driven. Now the reverse of this action—first the speed is slowed down, then the roller 115 disengages the brake lever, pressure is applied to the clutch sleeve to disengage the clutch that is disconnecting the power from the crank shaft of the machine, instantly the stop finger end 122 engages the clutch tooth 103 and the machine is stopped. The presser foot and thread handling means has had no action up to that time. Further upward movement of the starting rod causes the presser foot to be lifted from the work. With this action of lifting the presser foot the thread controlling means is operated.

Thus the machine can be started and stopped at all variations of speeds without raising the presser foot because it is the downward movement of the rod 137 that controls the speed of the machine and shifts the stop finger away from the stop clutch to varying degrees, the adjustments of the parts being such that when the stop finger is disengaged from the stop clutch, the machine operates at very slow speed; as it is gradually moved away from the clutch the speed is increased. The reversal of this action gradually slows down the speed until the machine is stopped. This refers of course to a slow movement by the foot of the operator; a fast movement by the foot of the operator will cause the machine to start at full speed instantly and come to a stop also instantly. The starting and stopping mechanism can be operated without operating the presser foot or thread pull-off means because the stop lever is under the control of the spring 126 and when the parts of the machine are in stopped position the end 136 of the rod is not yet in contact with the end 177 of the lever for actuating the foot or thread pull-off. To actuate these parts further upward movement of the parts is required.

50 The power transmitting mechanism.

Referring particularly to Figs. 1, 2, and 3 it will be seen that the power transmitter consists of a main bracket 143 secured to the under surface of the table 1 in any suitable manner, the bracket having an arm bored to receive a shaft 144. Upon this shaft is mounted a cone pulley 145 over which operates the belt 146 for transmitting power from any suitable line shaft to the pulley. This pulley 145 is provided with a frictional surface 147, co-acting with a similar frictional surface 148 of the driven pulley 149 also carried by the shaft 144. The belt 23 is driven by the pulley 149 for

operating the sewing machine. A bracketed lever 150 is carried by the rock shaft 151 supported in the arm 152 for rocking movement, and the forwardly projecting end 153 of the lever 150 has a suitable angular or camming face adapted upon rocking the lever inwardly to exert inward pressure on the cone pulley 145 thereby to force the frictional surfaces 147 and 148 together so as to clutch the pulleys 145 and 149 for rotation.

The shaft 151 has rockably supported thereon at 154 the lever 139, provided with a stud 155 to which is connected the upper end of a rod 156. The lower end is connected by a coupling 157 to a rod 158 connected to a floor treadle 159, whereby the transmitter may be operated in order to control the speed of the machine.

A brake lever 161 is also secured to the shaft 151, and the arm 152 is provided with a lug 162 having a spring 163 interposed between it and a lug 164 carried by the brake lever 161. The latter is provided with a frictional surface 165 to engage the rim 166 of the pulley 149 in order to quickly stop the pulley each time the rod 156 is thrust upward to shut off the power. Attached to the bracket 143 is projecting member 167 carrying a stub shaft 168 upon which rotates an idler pulley 169, which directs the upward run 170 of the belt 23 to the clutch wheel 93.

55 The speed regulator.

For regulating the speed of the pulley 149 and the speed of the sewing machine an adjusting screw 171 and lock nut 172 is provided, the screw being tapped into the lever 139 as shown in Figs. 1, 2, and 3. The inner end of the screw engages the lever 150 and by adjusting the screw 171 inwardly the frictional surfaces 147 and 148 are brought together with greater pressure so that increased speed is obtained. By reversing the adjustment the pressure on the frictional surfaces is decreased and slippage results so that the speed of the pulley 149 and the sewing machine is thereby reduced. This speed regulation is of great importance when operating upon difficult work, and particularly when an inexperienced operator is at the machine, inasmuch as without a speed regulator the machine is liable to start at the highest speed and the operator would lose control of the work. With the present improvement the requisite speed may be had by simple adjustment of the parts described to suit the desired or necessary conditions.

60 The power transmitting mechanism continued.

The lever 150 and the brake lever 161 are secured to the rock shaft 151 and hence a

downward pressure of the rod 156 swings the brake lever 161 away from the rim 166 somewhat before the frictional surfaces are brought firmly together. A reverse action of the rod 156 of course causes the frictional surfaces to separate prior to the effective operation of the brake lever 161 against the rim 166. Thus when the treadle is pushed down and the outer end of the lever 139 is shifted downwardly, the pulleys 145 and 149 will be clutched together thereby causing the transmitter to impart movement to the belt 23 in the direction of the arrows shown in Fig. 1, so as to rotate the clutch wheel 93. This operation will take place prior to any actuation of the stop lever 118 by virtue of the fact that during the initial downward movement of rod 134 the screw 132^a rides in the groove or flat surface 133. Upon a further downward movement of the foot treadle and the rod 156 connected therewith, the push and pull rod 134—137 will be shifted downwardly to a position where the shoulder 135 will strike the screw 132^a and swing the lever 118 downwardly on the pivots 119 thereby shifting the stop finger 122 out of engagement with the clutch tooth 103. Simultaneously with this movement the roller 115, which is normally at rest above and out of contact with the brake lifting lever 111, is shifted into engagement with the corner 115^a of the lever, thereby swinging the lever on the stud screw 112, lifting the pressure plug 107 slightly against the tension of the spring 106, and releasing the friction of the brake shoe 105 on the sleeve 90. This operation permits the spring 87 which is under tension to rock the sleeve 90 relatively to the shaft 71, thereby shifting the balls 91 into a clutching position, at which time the crank shaft is caused to rotate to start the machine.

The drive shaft mechanism continued.

It has been found in practice that where, as in the present case, the machine is controlled from the treadle 159 by the operator's foot, and where the brake or pressure plug lifting lever 111 and stop lever 118 are constructed substantially as in my aforesaid Patent #1,352,333, breakage of certain of the parts, particularly the lifting lever, often occurs due to the accidental shifting of the stop lever too far downward—such being ordinarily impossible when the same is mechanically and automatically controlled. Therefore in order to avoid such disadvantages, the lifting lever 111 in the present instance is provided with the segmental portion 113 concentric with the plane of movement of the roller 115 about the pivotal axis of the stop lever. The stop lever is furthermore operated by the rod 134 intermediate the stop finger and the fulcrum 114 (Fig. 38) thereby facilitating a positive operation and greater compactness of structure. Thus after the roller, as hereinbefore stated, engages the corner 115^a to shift or swing the lever 111 downwardly during any further downward movement of the stop lever 118 the roller 115 will merely travel over the curved surface 113 thus maintaining the lever 111 in a constant position without any further swinging movement thereof.

The speed regulator continued.

From the foregoing it will be understood that the speed regulator 171 not only provides a means for controlling the speed at which the machine is operated, but also, under one adjustment provides a means whereby the stop finger 122 may be brought out of engagement with the stop tooth 103 before the clutch wheel 93 is caused to rotate, or before the clutch wheel attains its maximum speed. Under another adjustment the clutch wheel may be caused to rotate at high speed before the stop finger 122 is brought out of engagement with the stop tooth 103. In such case the machine will start instantly at maximum speed, whereas under the other adjustments the machine will start gradually at varying speeds until it reaches the maximum speed. Thus it will be seen that I have provided a means for varying the speed of the machine from the minimum to the maximum for controlling the speed at which the machine is started and stopped and for starting and stopping instantaneously at any speed without shock.

Although the power transmitter herein shown and described in connection with the present improved machine is a desirable preferred operating instrumentality, it is of course understood that any other transmission may be used without departing from the spirit of the invention, or if desired under the particular circumstances the clutch wheel may be operated direct from a line shaft. In that case the clutch wheel will be in constant operation and the machine when started will always operate at a predetermined speed.

The presser foot and thread pull-off operating mechanism.

Referring particularly to Figs. 1, 3, 35, 36, and 43 the construction is such that the reverse action of the foot treadle is utilized not only for operating the transmitter and the clutch mechanism thereof, and the stop mechanism for the crank shaft, but also to lift the presser foot. That is to say, in the operation of stopping the machine by pressure of the heel on the foot treadle the presser foot may also if desired be lifted, the mechanism being such as to permit the machine to be stopped without raising the presser foot, except when desired. To accomplish this a rock lever 174 is mounted on a

pivot pin 175 supported by a bracket 176 secured to the top of the machine. One end 177 of this lever co-acts with the end 136 of the stop lever operating rod 134, the opposite end 178 of the lever overhanging and co-operating with one end 179 of the presser foot lifting lever 180, which is rockably or pivotally secured as at 181 to the overhanging arm 32 of the machine frame. The opposite end 182 of the presser lifting lever is slotted to straddle the presser bar 183, the projecting portions 184 being preferably rounded to co-act with the under surface of a presser bar guide 185 secured to the presser bar 183.

The guide has an extension 186 which fits into the slotted end 182 of the lever thereby preventing transverse movement of the same. The presser bar reciprocates vertically in a bushing 187 carried by the bearing 33 of the machine frame, and the presser foot 188 is secured to the bottom of the presser bar. A presser spring 189 is provided with its free end 190 resting on the presser bar guide 185, and its other end resting on the pin 191. Pressure is given to the spring intermediate its ends by an adjusting screw 192, Fig. 1, tapped into a lug 193 of the overhanging arm 32. Adjacent to the end 179 of the presser lifting lever 180 is a latch hook 194 rockably connected to the lever by a knurled headed shoulder screw 195. The lower end of the latch terminates in an ear 196 to which is attached one end of a coiled spring 197, the other end being attached at 198 to a washer clamped underneath a shoulder screw 199, and held against the face of the arm 32. The position of the spring is such as to hold the edge 200 of the latch in contact with the pin 191 as indicated in dotted lines in Fig. 35. The latch is also provided with a shoulder 201 adapted to co-act with a thread pull-off lever 205. The top of the latch is rounded out at 202 for engagement with a pin 203, thereby to normally hold the presser foot lifting lever 180 and the presser foot and the parts connected with it in the dotted line position shown in Figs. 35 and 36.

When the presser foot is lifted by the foot treadle, the levers 174 and 180, and the presser bar and presser foot shift to the dotted line position shown in Fig. 35, and tend to return to the full line position in Fig. 35 under the action of the presser spring 189. Co-acting with the shoulder 201 is a bent right angle portion 204 formed as a part of the thread pull-off lever 205 pivotally secured to the arm 32 by the shoulder screw 199. The free end of this lever terminates in a flared end 206 having thread eyes to receive the needle threads, and adjacent thereto are guiding strips 207, one on each side of the lever, extending upward and one overhanging the other at the top to guide the free

end of the lever 205. When the latter is actuated by the latch hook 194, and shifted to the dotted line position, slack thread is pulled off each time the presser foot is lifted.

The operation of the thread pull-off mechanism is as follows: The latch 194 carried by the lever 180 is moved downward when the presser foot is lifted, and the shoulder 201 is brought into engagement with the bent end 204 of the thread pull-off lever 205 and causes it to swing on the pivot 199 to the dotted line position shown in Fig. 35. When the lever 205 has reached the dotted line position, the curved face 200 of the latch 194 is brought into engagement with the pin 191 which swings the latch rearwardly on the lever 180 thereby disengaging the shoulder 201 from the bent end 204 of the lever, whereupon the lever 205 is released and returns to the full line position shown in Fig. 35. Thus the mechanism is such that upon reversing the treadle 159 sufficiently the presser foot will be elevated and at the same time the slack thread will be pulled off.

The feeding mechanism.

Referring particularly to Figs. 12, 13, 14, and 15 a four motion feeding mechanism co-acting with the presser foot is provided for feeding the work through the machine. This feeding mechanism embodies self locking adjusting means for regulating the length of stitch or the throw of the feed dog, such regulation being accomplished by an adjusting instrument, preferably as herein shown in the form of a key-wrench, thereby to prevent unauthorized persons from changing the length of stitch. Such adjusting means may preferably be so constructed as to be manipulated only by a special instrument, thus rendering it a simple matter to change the length of stitch merely by turning the adjusting means one way or the other to the desired position, as indicated by a gauge registering the length of stitch required.

The feed mechanism comprises a feed dog 208 which may be of any preferred form to suit the character of work. The shank 209 of the feed dog is slotted at 210 to receive a forward attaching screw, and also has an open ended slot 211 to receive the rear attaching screw. The attaching screws are tapped into the forward end 212 of the feed bar generally indicated at 213. The bottom surface of the feed dog is cut away at an angle at each side of the center line 214, to give free space at 215 and 216 to permit the feed dog to be tilted so that the toe of the feed dog will engage the work in advance of the heel, or vice versa, or to permit the feed to be leveled. These adjustments are obtained by adjusting the attaching screws as desired, as for instance, if the screw 217 is

loosened and the screw 218 is tightened, the toe of the feed will be tilted upward. If this adjustment is reversed the toe will be tilted downward, and the heel will engage 5 the work first.

By virtue of such adjustment the work may either be gathered or stretched, or fed out smoothly without either gathering or stretching. Furthermore after a predetermined adjustment of the feed has been made, 10 the feed may be removed at any time without destroying or disturbing such adjustment by merely removing the forward screw 217 without disturbing the rear screw 218, and withdrawing the feed dog 208 from the machine. The same may thereafter be replaced and at the same time maintaining 15 such predetermined adjustment, because the rear open slot 211 of the feed dog permits 20 the removal thereof without disturbing the screw 218.

The feed bar 213 is rockably supported in the cylinder 12 by a swinging yoke link 220 embracing the bar and supported by a stud screw 219. The yoke is connected to the feed bar 213 by a bolt 221 having a shoulder 222 operating in one side of the link, while a nut 223 having a shoulder 224 operates 25 in the opposite side of the link 220.

The feed bar is bored to receive an eccentric bushing 225, which is clamped between the inside faces of the yoke link by the bolt 221 which is screw threaded at 226 to receive the thread portion 227 of the bolt, 30 while the body 228 of the bolt fits freely into the other portion of the eccentric bushing. The shoulder 222 of the bolt and the shoulder 224 of the nut 223 clamp the bushing securely to the bolt and to the side 35 walls of the link 220, permitting the feed bar 213 to rock on the eccentric bushing. It will be seen that the construction is such that the height of the feed dog may be adjusted relative to the throat plate merely by turning 40 the eccentric 225. The cylinder 12 is provided with apertures 229 in each side wall through which may be inserted screw drivers to engage the heads of the bolt 221 and the nut 223, and by loosening the nut 45 and turning the bolt the eccentric will be turned with it so as to raise or lower the feed dog to the desired height. The adjustment is locked by holding the bolt with one screw driver and tightening the nut with another. Four-motion movements are transmitted to the feed bar by the ball crank 69 of the crank shaft operating in the bearing 230 of the feed lever 231. The rear end 50 232 of the feed bar 213 is connected to the feed lever 231 by means of a joint pin 233 secured in the feed lever 231. The feed lever has a plate 234 secured thereto which forms one wall of a slideway in which operates a slide block 235. This slide block is supported by and rocks on a stud screw 236

carried by arms 237 and 238 of an adjusting yoke 239 adjustably mounted on a vertical post 240 secured in the machine frame at 241 and 242. The post 240 is preferably tubular and the lower end is provided with 50 a flattened guide piece 243 secured in the tube by a pin 244, and projecting downward into a slot 245 of the rear end 232 of the feed bar and preventing lateral movement thereof. The forward end of the feed bar 75 213 is guided against lateral movement by the side walls 246 of a slot 247 formed in the end bearing 248.

The adjusting yoke 239 is slotted at 249 to receive a key nut 250 provided with a 80 flange 251 secured to the yoke by screws 252. The inner portion of the key nut is screw threaded to engage the left hand threads 254 on the lower end of a vertical screw 255, the upper end of which is provided with right hand threads 256 engaging corresponding threads in the post as at 257. The upper end of the screw 255 is provided with a flattened key 258 to receive a 85 key wrench 260 for turning the screw, the upper end of the post being bored at 259 to receive the wrench, and also bored to a larger diameter than the screw below the threaded portion 257.

In operation therefore in order to adjust the length of stitch or throw of the feed dog, it is merely necessary to insert the key wrench 260 into the post until the notch 261 engages the key 258 and then turn the screw in the desired direction 90 either to shift the adjusting yoke 239 up or down on the post, thereby lengthening or shortening the throw of the feed dog. Turning the screw to shift the yoke 239 and slide block 235 upward increases the amplitude of movement of the feed lever 231 thereby imparting increased movement to the feed bar 213 and to the feed dog 208. Adjustment in the opposite direction decreases the longitudinal movement of the feed dog due to the fact that as the slide block 235 is moved downwardly in the guideway an increasingly restricted lateral movement is imparted to the feed bar 213 by the feed lever 231 operating on the adjustable fulcrum formed by the rocking slide block 235. An adjustable collar 262 is mounted on the post 255 above the yoke 239 to limit the upward movement of the yoke when adjusted at the proper point. 100 The machine casting is provided with a projecting portion 263 against which the yoke may engage, thereby limiting the downward movement thereof. From this construction therefore it will be seen that the necessity of any locking means is obviated as the adjustment cannot change of itself. The stops 262 and 263 limit the feed dog movement in order to prevent it 105 from striking either end of the feed slots 110 115 120 125 130

- in the throat plate. The key wrench 260 is provided with a scale of graduations 260^a representing or indicating predetermined lengths of stitches or movements of feed, and such graduations register with an indicator 264 which aligns with the body of the key wrench when it is in position for adjusting the feed. Thus the key wrench and cooperating parts constitute not only 10 a means of accurate and minute adjustment of the length of stitch or movement of feed but also a micrometer gauge for measuring accurately to fractions of an inch the length of stitch at any time. It is merely necessary to insert the key wrench in position and the indicator will point to the proper graduation representing the exact length of stitch.
- 20 *The looper mechanism.*
- Referring to Figs. 16 to 27 inclusive it will be seen that the looper mechanism for cooperation with the needles in the formation of stitches, comprises in its preferred 25 form means for making preferably two parallel lines of double-thread-chain stitches, there being two loopers, each carrying a looper thread. The same mechanism may be used for making two lines of single-thread-chain stitches by omitting the looper threads. This looper mechanism can also be used for making what is commonly called the twin-needle, three-thread covering stitch having a thread carrying looper cooperating 30 with two spaced thread-carrying needles, wherein the formation of the stitch is accomplished by having the looper thread concatenated with each of the needle thread loops formed by the needle threads, leaving the looper thread lying in a zig-zag form from one line of needles stitches to the other. Such loopers may also be used with the vibrating needle or needles for the 35 purpose of making zig-zag stitches.
- 40 In the present instance a very simple high speed looper mechanism is provided which will operate one or more loopers, the same having means whereby each of the loopers may be adjusted to suit different needle gauges, or different kinds of stitch formation, the construction being such as to permit for instance the same pair of loopers to be adjusted to cooperate with needles spaced for making very narrow spaced rows 45 of stitches as well as very wide spaced rows. This is a very important improvement because machines now in commercial use require a variety of loopers sometimes as many as 25 or more different styles to accommodate various needle gauges, whereas in the present improvement a single style of looper may be used either for the front or back looper and furthermore may be adjusted to suit or accommodate any of the 50 needle gauges.

A four-motion elliptical movement is given to the loopers so that they travel in the rear of the needles when entering the needle loops as they move in one direction and return to their initial position in front of the needles, so that the needles coact with the back of the looper to enter between the looper and the looper thread.

In order that the loopers may co-act with thin or thick needles, I have provided an adjusting means to increase or decrease the movement of the loopers from front to rear of the needles, such means also being accessible to the operator from the outside of the machine. The elliptical movement of the loopers is obtained from a single crank and connection, connected in such a way with the crank shaft and side wall of the sewing machine as to provide a very rigid construction with a medium of weight.

The mechanism is operated by the ball crank 67 of the crank shaft, having connected thereto the ball joint 265 of the lever connection 266, the lower end of which has a ball socket 267 for receiving the ball 268 of an arm 269 clamped on the rock shaft 270 which is supported in the bearings 271 of a yoke bracket 272 provided with a tapered shank 273 adjustably secured in the wall 13 of the machine frame by two screws 274. By loosening these two screws, and inserting a screw driver in the slot 274^a, the yoke bracket 272 may be turned so as to tilt the position of the rock shaft 270 from the full line position indicated in Fig. 27 to the dotted line position, such line bearing the numeral 270^a corresponding to the axis of the shaft 270. When adjusted to the full line horizontal position the swinging movement of the ball 268 is perpendicular to the shaft 270, as represented by the full line 268^a in the diagram, Fig. 27, whereas if the shaft 270 is adjusted angularly as for instance to the dotted line position 270^b, the ball 268 will swing at an angle from the perpendicular, as represented by the dotted lines 268^b. The tapered shank of the yoke 273, is represented by the circle 273^a in the diagram. The arm 269 is clamped to the shaft 270 by a screw 275, and is held against sidewise movement by the bearings 271, one on each side of the arm.

The ball socket 267 comprises a cap forming the lower portion of the socket 276 secured to the connection 266 by screws 277. This cap is bifurcated to receive a block 278 pivotally supported by a pair of conical screws 279. Clamp screws 280 clamp the conical screws in adjusted position so that the block 278 may rock on the screws without side shake. This block is bored at right angles to the conical sockets for the screws to receive a looper shaft rocking pin 281 securely clamped to the rear end of the looper shaft 282 as by a clamp screw 283. The pin 130

- 281 is provided at one end with a head 284 to limit the endwise adjustment of the pin in one direction and to prevent the pin striking the inclined surface 285 of the cap 276. 5 In the present instance the looper shaft is made in two parts, the rear end 282 being of larger diameter than the forward extension 292, the parts being connected in any suitable manner.
- 10 The rear shaft portion 282 operates in a bearing 286 secured in the cylinder 12 by screws 287, the bearing having an opening 288 at the top to provide working space for the feed bar and having two saw cuts 289, in 15 the front and rear wall diametrically opposite the hole in which the shaft 282 operates. Clamping screws 290 are provided to adjust the saw cuts for adjusting the bearing 286 to fit the shaft 282 thereby taking up wear.
- 20 The rear wall of the bearing 286 is recessed at 291 to provide clearance for the bottom cap 276 of the ball socket.

Fig. 25 illustrates diagrammatically the operation of the looper operating means above described. The circle A indicates the motion of the ball crank 67, indicated by B. The line C represents the connection 266, and the ball 268 is represented by D, and the connection between the block 278 and the pin 30 281 is indicated by E. The direction of rotation of the crank shaft is indicated by the arrow in Fig. 25.

Referring to the diagrams of Fig. 25, the action of the looper operating means is as follows: As the shaft rotates from F to G the bottom end of the connection E shifts from the position H in the diagram to the position I, bringing the connection C to the perpendicular position, and the ball D upon 35 which the lever C is fulcrumed, from the central position J to the lowest position K. Further rotation of the shaft brings the crank B from the position G to the position L, and the connection E to the point M. Further rotation of the shaft brings the 40 crank B from the position L to the highest position N and the connection E to the position O, and the ball D to the position P.

Further rotation of the shaft brings the 50 crank B from the position N to the starting position B, and the ball D to the position J, and the connection E to the position H completing a cycle of movement which gives to the looper the elliptical movement as indicated by the lines Q of the diagram.

From the foregoing it will be seen that the ball 268 carried by the arm 269 secured to the rock shaft 270 forms a fulcrum for the lever connection 266 which is reciprocated by the ball crank 67, the center of the fulcrum formed by the ball 268 being relatively close to the connection made between the looper shaft pin 281 and the block 278. The vibratory movement of the loopers, indicated in the diagram of Fig. 25 at H and

M represents the movements of the looper from front to rear of the needle, while the movement of the looper into and out of the needle loops is indicated in the diagram at I and O. The path of movement of the 50 looper may be varied to accommodate varying needle sizes or thicknesses as shown by the diagrams of Figs. 26 and 27, one having a perpendicular line passing through the major axis of the elliptical path, and the other having an inclined line passing through the major axis of the elliptical path. The perpendicular position of the elliptical path represents the movement given to the loopers when coacting with a relatively thin 55 needle, while the angular position of the elliptical path represents the movement given to the loopers when operating with a thick needle. It will be seen that the distance from R to S is greater than the distance from T to U in Fig. 26, which distance is increased by reason of the shaft 70 being adjusted to the angular dotted line position 270^b shown in Fig. 27, whereby the ball 268 carried by the arm 269 swings on the angular line 268^b, thus shifting the elliptical path from the perpendicular to the angular position and utilizing a portion of the vertical reciprocation for the horizontal vibration of the looper.

The looper shaft therefore operates substantially at right angles to the connection 266, and substantially parallel to the horizontal position of the shaft 270. Furthermore if the connection 266 and the horizontal shaft 270 were shifted around 90°, then the vibrating movement of the looper would be represented by the major axis of the elliptical path shown in the diagrams, indicated by I and O, and the looper movement into and out of the needle loop would be reduced to the dimension indicated by H and M in the diagrams. On the other hand any path of movement between these two extremes could be had if the respective parts 95 were shifted to any angular position between the extremes above mentioned.

Thus where a relatively thin small gauge needle is used the movement of the looper from front to rear thereof is shown from W 100 to X in Fig. 26, while if a larger needle is used the required angular adjustment of the elliptical path of movement of the looper will increase the vibratory movement of the looper as from Y to Z, Fig. 26, so as to enable the same to co-act with the thicker needle at the front and rear thereof.

The forward end of the looper shaft 292 is supported in the bearing 248 secured in the cylinder 12 by the screws 293. Secured to the free end of the shaft 292 by the clamp screw 294 is a crank arm 295 to which is attached by a screw 297 for vertical adjustment a circular holder or carrier 296 for the loopers. The clamp screw 294 in the 125

aperture 289, Fig. 20 adjustably clamps the arm on the looper shaft, the sleeve having a saw cut 300 permitting this adjustment. The clamp screw 297 of the circular holder 5 for the loopers is screwed into the aperture 301 of the sleeve, and the side walls of the recess 302 straddle the side walls 303 of the lug 304 of the supporting arm for the looper carrier, permitting vertical adjustment of 10 the carrier and loopers. This circular or ring-shaped carrier or holder is cut away to form end portions 305 and 306 to give working space for the needles and loopers, and the hole 307 also provides clearance for 15 the needles. Adjacent to the end 305 are two tapped holes 308 for the reception of screws 309 and 310, one adjustably securing a thread carrying looper 311, and the other adjustably securing a like thread carrying 20 looper 312 to the front and rear walls of the ring-shaped looper carrier 296. In the description of the stitching mechanism the term "forward" is herein used to refer to the direction in which the looper 25 points, the term "backward" to the opposite direction of the looper movement. With reference to the terms front and rear of the needles, "front" is intended to mean the side facing the operator, while "rear" refers to 30 the reverse side of the needle.

The loopers 311 and 312 are identical and comprise a blade 313 terminating in a point 314, and a thread groove 315 extending from the front eye 316 to the rear eye 317. The 35 shank is segmentally slotted at 318 for the screws 309 and 310, and the bottom portion 319 of the shank is circularly formed in order to fit snugly against either the annular flange 320 on one side or the annular flange 321 on the other side of the carrier 296, thereby preventing the loopers from 40 movement relative to the carrier.

Thus it will be seen that I have provided a looper of very simple and durable construction, capable of a wide range of adjustment, whereby a single style or size of looper may be used with different needle gauges, or for different stitch formations, thus avoiding the necessity of providing 45 separate loopers of different sizes or shapes for every different spacing of needles or needle gauge or character of work.

The holes 322 adjacent to the end 306 of the ring-shaped or curved holder receive 50 screws 323 and 324 for adjustably attaching the needle guard holders 325 and 326, each holder having a bent wire 327, adjustably secured therein, so shaped as to act as a needle guard to control the needles in case they deflect out of the vertical path and to 55 position them properly with respect to the point of the looper; thus overcoming the skipping of stitches and breaking of needles.

The holders comprise a head 328 within

which the wires 327 are secured, and a flat shank 329 slotted at 330 for the reception of screw 323 or 324 for securely fastening the needle guide holders to the circular holder 296. The circular portions 331 of the shanks of the holders fit snugly 65 against the flanges of the carrier at 332 and 333 to prevent the guards 327 from shifting relatively to the carrier. Thus it will be seen from this construction that the needle guards may be adjusted as desired for all 70 needle gauges and for all sizes of needles, the needle guards and loopers being adjustable one relatively to the other or both relatively to each other.

The throat plate.

Co-acting with the stitching and feeding mechanism is a throat plate 334, see Fig. 31, secured to the forward bearing 248 by screws 335, Fig. 11. The throat plate is provided with the usual feed slots 337 through which operate the serrated surfaces 336 of the feed dog 208, see Fig. 12, the throat plate also being provided with the usual needle holes (not shown) through which the needles 90 operate. The throat plate is of segmental construction forming with the cylinder 12 a complete circle when attached thereto, the cylinder being cut away on the lines 338-338 to receive the throat plate. A 95 projecting tongue 338^a of the throat plate cooperates with a groove formed in the cylinder, Fig. 17, so that the projecting portion 339 overlaps the tongue 338^a, thereby securely holding the rear end of the plate 100 from tipping or moving when the pressure of the foot is brought to bear upon the outer overhanging end of the throat plate.

Referring particularly to Figs. 1, 3, and 5, the forwardly extending end 340 of the throat plate is provided with beveled or inclined edges 341, and an end cap or cover 343 fits thereover, the dove-tailed grooves 342 of the cap cooperating with the inclined portions 341, and hence the same may be 105 shifted on and off the forward end of the throat plate. The side walls of the cap at 344 are partially slotted to make them flexible so that the cap will yield and properly fit over the beveled or inclined edges of the throat plate. The end cap is hollow to provide free working space for the loopers and other parts adjacent thereto. In order to secure the cap 343 to the cylinder and prevent it from becoming disengaged from the 110 throat plate during the operation of the machine the cap is provided with suitable locking means comprising a lock spring 343^b projecting through an opening 343^a for convenient manipulation by the operator, the cap being removed by pressing inward 115 on the spring to disengage the hook end 343^c from a notch 343^d formed in the side

wall of the cylinder 12, see Figs. 16 and 17. This lock spring is suitably secured inside of the end cap as by a screw 343, Fig. 5.

The cylinder work arm.

As illustrated in Figs. 1 and 31, the cylinder 12 may be provided at its forward end with a projecting portion 345 extending outwardly to correspond in length approximately with the overhanging portion 340 of the throat plate, the extension 345 being provided with an end wall 346 to prevent lubricant from escaping. The curved side walls 347 of this extension are adapted to lie in juxtaposition to the curved walls of the cap 343 thereby forming a support upon which the bottom edge 348 of the end cap rests.

It will be seen that by reason of the fact that the feeding and looper mechanisms are arranged and supported within the cylinder 12, the same having the enlarged opening 12^a covered by the throat plate extending a considerable distance in the rear of the needles I may do away with the use of a cover plate, and as a result of this construction greater rigidity of the parts is secured, as well as free access to the interior of the cylinder, thus eliminating loose parts with the added advantage of using a cylinder of equal diameter throughout its length.

The cylinder is preferably constructed of steel tubing of small diameter. Small tubular work may be handled with greater facility than with the usual cast cylinder which is tapered from the free end toward the machine frame, and at the same time giving the increased advantage of greater strength and rigidity. In the present machine the cylinder is detachably secured in the boss 11 by spot clamping screws 349, permitting the cylinder to be removed and replaced by disconnecting the operating means for the looper and feed within the rear trunk of the machine. To prevent the leakage of oil between the cylinder 12 and the boss 11 a wick insert 350 of suitable material is provided which fits into a groove of the cylinder 12 to form a leak-proof joint between the parts.

The looper controlling mechanism.

Referring to Figs. 3, 28, 29, 30, 31, 32, 33, and 34, improved means for controlling the looper threads is provided. Secured to the end bearing 248 is a two-arm rock lever 351, supported by the shoulder screw 352 screw threaded into the end bearing. An arm 353 of the rock lever carries at its free end a flared portion 354, projecting from one side thereof and having a tapered inclined or cam surface 355 terminating in a flat surface 356, Fig. 29. The upper edge 357 of the arm 353 is adapted to co-act with the rounded end 358 of a cam 359 adjustably

secured to the looper shaft 292 adjacent to the outside face of the end bearing 248 by set screws passing through the tapped holes 360. The cam 359 rocks the lever on the screw 352 as required to control the looper thread or threads, and swings the lever downwardly away from the looper shaft 292. On the return movement, in order to keep the lever in contact with the co-acting surface of the cam a flat spring 361, having its free end resting against the upper portion 362 of an arm 363 of the rock lever 351 is provided. This spring is clamped by a screw 364 into a T-slot 365 of the end bearing 248, as shown in Fig. 31. The spring 361 has a plate 366 attached to it to provide a better clamping surface for the screw 364. At the top of the arm 363 I provide, adjacent to the portion 362 co-acting with the spring, a wall 367 having an aperture 368 to receive the body 369 of the screw 370, while an opposed wall 371 has an aligned aperture screw threaded to receive the threaded end 372 of the screw 370. The walls 367 and 371 are spaced at 373 to receive a rocking plate 374 having an aperture 375 for the screw 370 which rockably supports the plate. The purpose of this rocking plate 374 is to act upon the looper threads and clamp them against the surface 376 of the inner wall of the cylinder 12. The wall 371 is cut out to form two lugs 377 and a space 378 therebetween for the passage of thread, these lugs or projections 377 acting as separators for the looper threads to prevent them from tangling and to so control and guide the threads one above and the other below the center line of the rocking plate 374 that equal pressure will be imparted to each thread irrespective of the diameters of the threads relative to each other.

Adjacent to the wall 371 is a slot 379 and an opposed wall 380 is provided with a thread eye, and an inclined thread slot 381 in the right angled wall 383 leading to the top edge 382 permits the threading of the eyelet in the wall 380. The wall 383 has a second slot 384 leading from the thread hole 385 in the end wall 386, and also emerging at the top 382 to permit the thread to be inserted in the hole 385.

Between the walls 380 and 386 operates the looper thread take-up or controller, comprising a circular shank at 387 provided with an elongated slot 388, through which passes a clamp screw 389, Fig. 1, for securing it to the rounded surface 390 of the arm 295, Fig. 20, carrying the loopers, the screw 389 fitting into the tapped hole 391. The thread controller is curved at 392, reversely to the curve at 387 and is bent in a half-loop at 393, and forms with a curved portion 394, a neck 396, and a curved-shoulder 395, terminating in a point 397. The con-

troller is so shaped as to properly act upon the looper thread or threads for controlling the same during the stitch formation.

From the foregoing it will be seen that I have provided a very simple, compact, and reliable means for controlling the looper threads, accessibly located in and covered by the end cap of the machine, and comprising a thread clamp or nipper 374 and a thread take-up or controller 387 to give and take-up thread at the desired intervals of each stitch forming cycle. The improved location of the parts offers advantages in threading and adjustment, one of the important advantages residing in the fact that when the looper thread breaks, the broken end of the thread usually lies close to the looper and hence rethreading in the present machine is easy due to the convenient location of the parts. Heretofore thread controlling mechanisms have been located in the cylinder or at the rear of the machine, thereby rendering the parts very inaccessible. Usually action on the thread of the thread-controlling mechanism causes breakage of the thread where weak spots or knots occur in the thread, and when so located, loss of time occurred in the rethreading. All such loss of time is done away with in the present improvement on account of the thread-controller being located at the stitching position. By reason of this construction it is possible to time the action of the cam 359 with respect to the movement of the loopers so that its end 358 will co-act with the arm 353 of the lever 351 to permit the nipper or clamp 374 to hold the looper threads tightly between the surfaces 398 and 376 while the looper is moving rearwardly out of the needle loops and so hold them until the point of the needle has passed between the looper and a strand of the looper thread. That is to say the clamp is closed upon each looper thread 399 while the thread remains in the neck 396 of the controller during the backward movement of the loopers, and that portion of each looper thread which extends from the thread clamp through the eye of each looper and up to the preceding stitch is drawn backward free from slack, as shown at 400 in Fig. 30. Immediately upon the point of the needle reaching the position in Fig. 30 the end 358 of the cam contacts with the inclined surface 355 of the lever 351 and swings it downwardly to the dotted line position 401, Fig. 30, thereby releasing the grip of the thread clamp upon the looper thread. The cam swings further in the direction of the arrow upon the flat portion 356, and thereupon moves backward while the looper is passing from the front to the rear of the needle, thus causing the surface 358 of the cam to travel directly over the surface 357 of the arm 353 to hold it down against the action of the

spring 361 until the cam reaches the position in Fig. 28, representing the extreme forward movement of the looper. During this forward movement the thread clamp is held open or released to permit the free movement of the looper thread for the formation of the next stitches.

Simultaneously as the loopers reach the end of this forward movement as in Fig. 28, the loopers are shifted from the rear to the front side of the needle, thus shifting the end 358 of the cam off of the surface 357 at which time the spring 361 swings the lever 351 upwardly and closes the thread clamp; holding it closed during the backward movement of the looper out of the needle loops, and until the needle point has passed down between the back of the looper and a strand of the looper thread.

The action of the thread controller in conjunction with the thread clamp is such as to act upon the looper threads to take up the slack during the backward movement of the loopers, and simultaneously as the thread clamp opens the loops 400 of the looper threads are in such position where they slide out of the neck 396 over the curved shoulder 395 and during a further backward movement of the loopers the loops are drawn up into the bend 393 of the thread-controller as shown in Fig. 32. The looper threads remain in such position during the forward movement of the loopers, the same drawing the needed thread from the supply through the thread eye 385, and holding the thread so that it will positively draw through the neck 396. As the loopers reach their extreme forward position, as indicated in Fig. 28, and simultaneously as they shift from rear to front of the needles, for the return movement, the thread clamp 374, as hereinbefore described closes upon the threads, and inasmuch as the strands of the looper threads 399, extending from the hole in the wall 380 to the hole in the wall 386, lie in the neck 396, the same are carried downward in an inwardly curving path to the position indicated at 400, whereupon the nipper or thread clamp is released or opens and the threads are cast off, thereby giving the necessary slack thread for the tying of the stitches.

Thus it will be seen that the arrangement of the looper thread controlling parts is such as to positively act upon the looper threads to control the slack, and after the slack has been controlled, the controller 387 reaches a position where the thread is automatically cast out of the neck 396, due to the angular relation between the thread guides and the position the neck 396 assumes after the needle has entered, as in Fig. 30, between the looper and looper thread during the stitch-forming cycle.

Referring to Figs. 3, 7, 8, 24, 31, and 34, in

order to conduct the looper threads 399 from the supply to the thread controlling mechanism, two thread tubes 404 are provided which extend from the rear through the machine housing, and through the cylinder 12 where the forward ends 406 terminate close to the thread controlling means. This arrangement offers the advantage of conducting each thread separately from a position close to the supply, through the interior of the machine, and keeps them entirely protected from the operating mechanism, and also prevents any lint carried through by the thread from accumulating in the machine. The threads are thus separately encased or housed throughout substantially the length of their travel. Two apertures 402 (Fig. 7) are provided in the lower portion of the cover plate 7 through which project the ends 403 (Fig. 8) of the thread tubes 404. The bearing 286 is slotted at 405 (Fig. 24) to permit the tubes to pass therethrough one above the other.

The end bearing 248 is also cut out as shown in Fig. 31 to permit the thread tubes 404 to pass between the inside wall of the cylinder 12 and the end bearing. The outlet ends of the tube 406 are located adjacent to the elongated slot 407 provided in the wall of the cylinder 12 to permit threading wires to be inserted in the tubes 404 for drawing the end of the thread through. An angular saw-cut 408 extending from the elongated slot to the edge of the cylinder permits the threads to be placed in between the wall 376 of the cylinder and the surface 398 of the controller clamp 374.

The needle thread control.

For the top needle thread control a bracket 409 is attached to the top of the cover plate 7, Figs. 1 and 35, which carries suitable tensions 410, three in number, and the usual nut and spring 411 for regulating the tension on the threads. A pin 412 carried by the bracket 409 extends into a U-shaped opening in the bottom of the tension plates to prevent their turning on the center studs 411, while the upper ends have a pin 413 carried by one of the outside plates and extending freely through the intermediate plate and the usual outside plate, permitting the plates to be separated for inserting the threads between them. The object of this pin 413 is to prevent the threads from being withdrawn from between the plates when they are drawn upward for the purpose of providing slack thread at the end of each stitching operation. The threads 414 are conducted from the supply through the guide eyes 415 of the bracket 409 in between the two outside and intermediate tension plates 410 and through the guide eyes 416 in the right-angled bent end 206 of the thread pull-off lever 205. Thence they are

conducted through the guide eyes 418 of a stationary eyelet also secured to the bracket 409 adjacent to the guide plates 207, which as hereinbefore described straddle the free end of the lever 205 to guide it in its movements.

A thread guide 417 is attached at its forward end to an angle bracket 419 secured to the top portion of the frame above the rectangular opening 34. The threads enter eyelets in the end 420 of the thread guide 417 which is slotted forming troughs for the threads throughout its length, except for the thread holes 421 at the forward end from which the threads emerge and are led to thread eyes 422 of a thread carrier 423 carried by the end 424 of the link pin 46. From the thread eyes 422 the threads pass downward in through the eyes of the needles 51.

As the result of this mechanism for controlling and guiding the top thread from the supply to the needles an almost perfect control is obtained, and at no time during the stitch forming cycle or movement of the parts does the thread become slack or out of control. The relation of the guide eyelets with the end of the trough shaped thread guide 417 is such that the threads are entirely protected by passing through the thread trough guide from the thread eyes at 420 to the thread eyes at 421. The space from the thread eyes at 421 to the thread eyes at 422 permits a slight take-up action to the thread, which is desirable due to the fact that the thread carrier 423 is reciprocated with the needle bar, the thread eyes 422 thus having a reciprocatory movement relative to the stationary thread eyelets 421.

One advantage of the trough shaped thread guide 417, extending lengthwise of the arm 32 of the machine frame, resides in the fact that it enables the operator to place articles that are being stitched or have been stitched, such as shoe uppers and the like, up over the head 33 and permit them to rest on the arm 32 until the arm is completely filled with such articles while other work or articles may be passed over the cylinder 12 until that becomes filled. All the articles may then be removed from the cylinder 12 and the arm 32 at the same time, thus reducing to a minimum the frequency of lifting the presser foot and breaking the stitches extending from one piece to another. As a result the machine may be kept in more continuous operation, one piece of goods being stitched directly after another, and without stopping the machine until a large number of pieces have been completed. Thereupon by raising the presser foot and breaking the threads, all of the work may be removed at one time. The overhanging arm 32 and the head 33 are so constructed that very small articles may be passed over these

parts, as well as over the cylinder 12. Another advantage of this construction is that the line of vision of the operator is not obstructed, permitting the inspection of the work immediately as it feeds from under the presser foot, during the operation of the machine.

The lubricating mechanism.

As illustrated particularly in Figs. 7, 8, 10, 11, 40, 41, and 42, this improved machine is provided with an automatic lubricating mechanism, which comprises a suitable pump to deliver oil from the bottom reservoir to a reservoir at the top of the machine, from which the oil is conducted to each of the bearings through tubular conduits, or otherwise. This lubricating means supplies oil for the oil buffer and provides a shock absorbing fluid to and between the surfaces of parts subject to shock in the starting and stopping, as well as shocks caused by the rapid reciprocation and rotary movements of other parts. It also obviates the necessity of oiling the machine several times each day, as practically all of the parts requiring constant lubrication are located inside the machine frame, thus preventing any of the flying oil escaping to the outside of the machine where it would be injurious to the goods, and objectionable to the operator. The lubricating system employed is an improvement in part over that shown and described in my Patent No. 1,348,527, of August 3, 1920, certain other changes and modifications being made to adapt it to the present machine. In the patent referred to, I employed a top and bottom hollow arm, a needle drive shaft rotating in a tube, and a looper shaft operating in a tube, each of the shafts being of tubular construction and the lubricant being conducted through the hollow shafts. In the present improvement however the overhanging arm of the machine is of L-shape construction and the needle driving means has a rock shaft instead of a rotary shaft. The needle bar is operated through an oscillating arm 41 carried by the shaft, and as a result of this construction the frame structure is considerably reduced in size due for instance to the elimination of the usual gearing and crank mechanism for reciprocating the needle bar. A simple means is also provided for lubricating the needle bar, which means is independent of the lubricating means for the major parts of the machine. The looper and feeding mechanisms operating within the cylinder are automatically lubricated, as well as the other parts within the machine frame. Thus the only parts which need to be lubricated with the hand oil cup are the needle bar, needle bar driving link or arm, and the forward bearing of the rock shaft.

All the other active parts being encased are automatically lubricated.

In the patent above referred to a detachable reservoir and filter for the lubricant was used, the same being placed underneath the trunk opening of the machine frame. In the present construction the frame itself forms a reservoir having the four sides and the bottom integral, and when the rear cover plate is applied, the entire structure is enclosed and is sealed against leakage.

In the present improvement the lubricating system comprises a pump belt wheel 425 carried by the shaft 426. At the end of this shaft is attached a small gear 427 which is in mesh with and drives a similar gear 428 carried by a shaft 429. These gears operate in a suitable recess of the pump casing 31 secured in the boss 30 by a set screw 430. The pump casing is provided with a peripheral groove filled with wicking 431 for making a leak proof fit between the casing and the hole into which it fits. The gears are covered by a circular plate 432 secured to the pump casing 31 by screws 433, a packing plate 434 being interposed between the plate 432 and the pump casing to make it air tight.

The plate 432 is provided with an inlet for the lubricant which is drawn in by the gears and forced up by the tube 435 which has an angular bend 436 and a vertical portion 437. This tube is secured at 438 in the bottom wall of the reservoir 439. The upper end 440 of the tube projects through the bottom 441 of a filter made of very fine wire mesh screen, the filter having the side walls bent up, as indicated at 442 to fit snugly within the walls of the reservoir 439. The oil forced up by the pump through the tube 437 and out of the end 440 lifts the oil gauge plunger to the dotted line position 444 of Fig. 42, the oil striking the collar 445 and lifting the gauge as shown. The depending stem 446 of the gauge is provided with one or more flutes to permit the passage of oil into the reservoir between the stem and the inside walls of the tube 438. Thus the gauge indicates to the operator the flow of oil, as each time the machine is started the gauge is lifted to the dotted line position, irrespective of the speed at which the machine is operated.

When there is not sufficient oil in the reservoir to supply all the parts of the machine, air is admitted in the opening of the circular plate 432, through which the oil enters, and such air will escape from the end 440 of the tube without lifting the gauge 443 above the top cover plate 447, which covers the opening through which the reservoir is inserted into the top frame portion of the machine. The cover plate is held in place by a shoulder screw 448 on one corner and a thumb screw 449 at

the other corner, and may be swung laterally on the screw 448 by loosening the screw 449 and swinging the cover to one side for removal of the reservoir or filter. The gauge 443 operates through a hole in the cover plate as shown by the sectional view. The filtering screen 441 is of suitable depth to contain a quantity of oil and is at the same time so located as to permit a space for 10 lubricant to be distributed to the various tubular outlets, or parts indicated at 451, 452, 453, and 454, each of which having its delivery end so located as to deliver oil therefrom to the respective bearings. The 15 bottom wall of the reservoir is also provided with one or more holes (not shown), through which the oil may escape to lubricate other bearings which can be reached without the aid of depending tubes. The 20 tube 454 leads oil to the funnel 455 carried by the horizontal tube 456, the end 457 directing lubricant to the bushing 15, and the opposite end 458 directing lubricant to the bushing 101^a. The oil escapes from holes 25 in the bottom of the reservoir to supply the needle rock shaft connection 59 and the rear bearing 37.

The tube 451 supplies the intermediate bearings of the crank shaft 63. The tube 30 453 supplies the crank 67, the looper actuating mechanism, and the mechanism below it. The tube 453 supplies the crank 69 and the feeding mechanism with lubricant. A portion 35 of the lubricant thrown from the cranks 67 and 69 is caught by the pocket 118^b and oils the pivots 119, see Fig. 37. Other portions are caught upon the plate 459 secured to the cover plate 7 by screws 460, and which has a tapered extension which terminates 40 in a spout end 461 for delivering lubricant directly to the reservoir 125 of the stop lever 118, which supplies the oil buffer 124 of the stop lever, see Figs. 7 and 40. The oil buffer 124 is connected with the reservoir 125 by 45 holes 124^a leading from the chamber of one to the other for the passage of oil.

The bushing 15 is supplied with lubricant from the end 457 of the horizontal tube 456 and has a recess 462 to receive the lubricant. 50 Thence it flows down through the hole 463 directly on the shaft 62. The lubricant escapes from around the shaft through the annular groove 78, returns through the horizontal outlet 464, and escapes at 465 into the interior of the machine, see Figs. 11 and 40. The oil delivered from the outlet 458 into the hole 466 of the bushing 101^a is led directly to the end portion of the shaft 70, which is drilled at 466^a to conduct the lubricant to the center 467 of the hollow stop clutch shaft 71. The lubricant escapes at 468 to lubricate the bearing 25 of the shaft in the bushing 99, and the escaping lubricant is caught in a receptacle 469, and thence

passes through the tubular outlet 470 into 65 the interior of the machine.

Some of the oil which escapes to the belt wheel 93 is thrown off by the flanges 471 and is caught inside the belt wheel guard 22 by the hollow receptacle. Another portion which may be thrown off by the wheel or the belt is caught in the lower hollow projection 472, having a tubular outlet 473 leading to the interior of the machine. The tubular outlets 470 and 473 projecting from 70 the receptacles 469 and 472 deliver the lubricant caught thereby through the rectangular opening 24 in the side wall of the machine frame. Other portions of the lubricant that escape from the opposite side of the wheel 75 are caught by the inner wall of the projecting rib 17 and also conducted to the interior of the machine. The upper edge of the rectangular opening 24, as indicated at 474, Fig. 41 is beveled from the outside to the 80 inside so that the drippings of oil will fall to the interior of the frame. The drive belt 23, the downward run of which operates the pump wheel 425 is also located inside of 85 the belt wheel guard 22.

When the belt wheel 23 is put in operation by the transmitter, the pump will supply the reservoir at the top of the machine, the pump being operated independently of the driven mechanism of the machine, the operation of the same depending upon the operation of the treadle by the operator. This is an important advantage because the machine is sure to be lubricated before it is operated, thus minimizing the liability of the machine 90 being operated with any of the bearings dry.

In order to conduct the lubricant into the cylinder 12 for lubricating the parts contained therein, the feed bar is made trough-shaped at 475 and 476, see Fig. 12, so that the lubricant will flow down the inclined surface 477 of the feed bar 213, see Fig. 15, into the troughs 475 and 476. These are connected by a channel 478 having an opening at 479 to lubricate the bushing 225 which 100 supports the feed bar. A part of the lubricant flows down the link 220 to lubricate its bearing on the stud screw 219, and portions flow out through the opening 480, Fig. 115, passing through the side walls of the bearing 248, which guides the forward end of the feed bar. The portion 481 between the looper shaft bearing and the slot for the feed bar is provided with a hole or slot for the passage of lubricant into the looper shaft 120 bearing. A portion of the lubricant escapes along the looper shaft onto the cam 359 and lubricates the frictional surfaces of the parts of the thread controlling mechanism located within the end cap of the machine. A portion 125 of the lubricant is caught in the extension of the cylinder and prevented from escape by the end wall 346, Fig. 31. A return

passage 482 is provided in the end bearing 248 to permit the lubricant to return from the inside of the cylinder to the interior of the machine by passing through a slot 405, Fig. 24, through which the thread tubes 404 pass. In order to accomplish the return of the lubricant from the mechanisms at the front end of the cylinder, the machine is mounted on the table at a slight angle, the free end of the cylinder 12 being slightly higher than the inner end so that the lubricant will flow to the interior of the machine.

Although, in the present improvement, a rotary pump is preferably used, any form of pump may be used for the purpose. Also the pump may be operated otherwise than from the drive belt of the sewing machine, as for instance a reciprocating pump may be operated from some part of the interior mechanisms, or from the push and pull rod 134, but the present rotary mechanism controlled independent of the machine is preferred on account of its great simplicity, and reliability. The power required to operate the pump is negligible since the gears are of such tiny proportions, being preferably $\frac{1}{16}$ inch in diameter and $\frac{3}{32}$ inch thick, and at the same time they produce an ample supply of lubricant at any speed to meet the requirements.

The cross stitch mechanism.

The cross stitch mechanism for laying a thread in the path of the needles on top of the work, in alternating loop form is an improvement over the mechanism described in my co-pending application, Serial No. 456,729, filed March 29, 1921. In the present machine however improved mechanism for driving the gears in the presser foot is provided over my aforesaid application, and the presser foot is hinged to yield from front to rear in the direction of the feed of the goods in order to ride more freely over seams and uneven thicknesses of work.

Referring particularly to Figs. 43 to 46 inclusive, the mechanism comprises a driving gear 483 carried by or made integral with the flange 66 of the crank shaft. This driving gear meshes with a similar gear 484 of equal diameter secured to a shaft 485 by screws 486. These gears are located within the machine frame and the shaft 485 is given a rotary movement thereby. The shaft is supported in the rear bearing 487 and in the forward bearing 488, the bearings being secured in a horizontal tube 489 cast in the L-shape section 32 of the machine frame. A hole is thus left for the shaft thereby saving the expense of drilling the same. To make the hole in the casting with a sand core was also found impracticable. But by casting the metal around the steel tubing as in the present instance the cost is greatly reduced, the overhanging arm is strengthened, and

it is merely necessary to enlarge each end of the tube in order to insert the bearings 487 and 488 for the shaft. This construction has the advantage of reducing the friction of the shaft and provides adequate space 490 70 for lubricant, which is supplied automatically, to pass from one bearing to the other. The forward end of the shaft carries a thread controller 491 adjustably secured thereto by the screw 492. The thread controller operates on the top thread (not shown) as it is conducted from the supply to the presser foot, and is fully described in my aforesaid pending application.

Adjacent to the forward end of the bearing 488 is located a gear 493 secured to the shaft 485 by screws 494. This gear is in mesh with a gear 495 of equal diameter secured by screws 496 to the upper end of a vertical rotary operating shaft 497 for the rotary cross thread mechanism. This shaft is located in the hollow or tubular presser bar 183 and has a bearing 498 in the upper end of the tube or bar 183 and a bearing 499 in the lower end of the tube. Intermediate 80 these bearings the shaft is reduced in diameter as at 500 to increase the flexibility of the shaft and to reduce friction. The presser bar or tube reciprocates vertically in the bushing 187 and is controlled by the guides 185 and 186 as hereinbefore described. The lower end 502 of the presser tube 183 is counterbored vertically at 503 receive a coil spring 501. The top portion of the coil spring rests against the shoulder formed by the counterbore and the lower end rests against a flange 504 formed as a part of the shaft 497. Projecting from the flange is a semi-circular key 505 which fits into a semi-circular key hole provided in a gear 506 in 90 mesh with an intermediate gear 507 rotating on the stem 508 of the screw 509. The intermediate gear 507 is in mesh with and drives a ring gear 511 which carries a rotary circular plate 512 provided with 100 upstanding thread carrying lugs 513 for forming loops in the top thread. Co-acting with the lugs is a cast-off 514, integral with the ring 515. The ring gear 511 rotates in a 110 socket in the presser foot, and the overhanging head 510 of the screw 509 impinges upon the flange of the ring 515 to hold the ring gear in position. This screw also acts as a pivot for the intermediate gear and as a locking means for the bottom 517 provided with beveled edges fitting into the presser foot 516, the stem 508 entering the hole 518 in the bottom 517. Thus the rotary cross thread carrier 512 having its axis substantially alined with the axis of the needle bar is provided with projecting lugs 513 movable in a continuous, circular, or rotary path around the needles. These lugs are adapted to engage the thread from the thread guide 526 (hereinafter described) and carry the 120 130 139

same to a loop forming position, the cast-off member 514 being effective at the desired times to cast off the thread from the loop forming lugs.

5 *The presser foot.*

The presser foot 516 is hinged to a yoke holder 522 by shoulder screws 521, one arm of the yoke being connected at 519 and the other arm at 520 to the sides of the presser foot, enabling the presser foot to rock slightly on the screws. Each of the arms has an overhanging shoulder 523 to contact with and limit the rocking movement of the presser foot. The yoke 522 is clamped to the presser tube or bar 183 by a screw 524 passing through the slotted rear walls, a space 525 permitting the heel of the foot to rise slightly when passing over seams. An eyelet 526 formed in one of the arms of the presser foot yoke guides the top thread into position for stitching formation, the same being preferably located to one side and slightly to the rear of a needle.

25 The object of the spring 501 acting between the shoulder 503 and the flange 504 is to give a slight downward pressure to the shaft 497 and hold the gear 495 in proper relation with the gear 493 to yield downwardly when a seam is passing under the toe of the presser foot, and to yield upwardly when a seam is passing under the heel of the foot. A more detailed description of the rotary cross stitch forming mechanism carried by the presser foot is deemed unnecessary since the same is fully described in my aforesaid co-pending application.

40 *The cross stitch mechanism continued and the needle vibrating mechanism.*

This cross stitch driving mechanism is also useful for operating a trimmer, top feed, ruffler, or other attachments as in the present improvement it is utilized for operating a zig-zag needle. The zig-zag stitching mechanism cooperates with the looper mechanism, two forms of vibrating needle mechanisms being herein shown, one thereof swinging in a horizontal center located approximately mid-way between the ends of the needle bar, so as to swing upon the center to space the stitches as desired, the other comprising a right angle slide adapted to vibrate the needle and needle bar at right angles to the direction of the reciprocation. For certain classes of work the right angle movement is superior to the swinging movement, the swinging movement however being capable of a higher speed and therefore superior for light materials where a narrow vibration or bight of stitch is suitable.

Referring to Figs. 47 to 49 inclusive, in order to vibrate the needle the same gearing construction as shown and described in con-

nection with the cross thread laying mechanism may be employed except that the gear 484 would have twice as many teeth as the gear 483, to give a two-to-one reduction to the shaft 485. That is to say the shaft would operate at half the speed of the crank shaft of the machine. At the forward end of the shaft 485 is located a triangular cam 527 secured to the shaft by screws 528 passing through the flange 529 of the cam. This cam operates in a fork 530 which straddles the cam, the fork being carried by the arm 531 which extends downwardly and is secured at 532 by screws 533 to the boss 534 of the swinging bearing 535. The swinging bearing 535 is bored to receive the lower and upper bushings 53 and 54 (Fig. 6) for guiding the needle bar 48, and has a tapered circular disc 536 integral therewith which is seated in a circular socket 537 formed in the face 538 of the head 33 of the machine frame. One-half of the circular socket is formed with a beveled circular plate 539 secured by screws 540, so that the swinging bearing may rock therein and be secured against shake or lost motion.

The second form of mechanism for vibrating the needle above mentioned comprises a shoulder screw 541 and a block 542 supported by it and operating in an elongated slot 543 of the arm 531. The lower end of the arm carries a shoulder screw 544 to which is connected the arm 545 of the right angle dove-tailed slide 546. The slide is integral with a needle bar bearing 547 carrying the bushings 53 and 54 for guiding the needle bar. This dove-tailed slide 546 is guided by a beveled edge plate 548 which is secured by screws 549 to the wall 538 of the end bearing 33 of the machine frame. The right-angle slide construction permits the needle bar to be shifted laterally while it reciprocates in a vertical plane. The link connection 45 with its joint pins 44 and 46 permits either right angle movement or swinging movement as the case may be. The extent of the movement of the needle bar may be varied by substituting cams 527 of different throws. From the foregoing it will be seen that I have produced a very simple mechanism for making zig-zag stitches by giving right line or angular movements to a reciprocating needle bar and at the same time a portion of the operating means may be used to equal advantage for operating a cross-thread ornamental stitch-forming mechanism.

The crank shaft continued.

It will be noted that by making the crank shaft in two sections so that the stop clutch shaft is separate and detachable from the main crank shaft, an important advantage is derived over a construction wherein the shaft is made as one part. By virtue of this

improvement the necessity of removing many parts is avoided when changing or replacing the cam block, and as a result no skill is required merely to remove the bushing 99 and draw the stop clutch shaft outward with the fingers. Thus the changing of the cam block and re-assemblage is quickly accomplished, as all other parts are so arranged as to remain in their working position while the shaft is removed or being replaced. A groove or slot 84^a is provided in the enlarged section 85 of the stop clutch shaft in order to provide clearance for the wedge balls 91 when withdrawing the shaft section 85.

Although I have described my invention in its preferred form it is to be understood that I do not limit myself to the construction herein shown and described except in so far as defined in the claims and embraced within the scope thereof, and reference is hereby made to my contemporaneously pending divisional applications wherein certain of the improvements shown and described herein are claimed, to wit: Allowed applications for improvement in feeding mechanism for sewing machines, Serial No. 667,453, filed Oct. 9, 1923; for improvement in looper mechanism for sewing machines, Serial No. 667,454, filed Oct. 9, 1923; for sewing machine, Serial No. 671,874, filed October 31, 1923; for improvement in lubricating mechanism for sewing machines, Serial No. 678,398, filed December 4, 1923; for improvement in sewing machines, Serial No. 678,399, filed December 4, 1923; for improvement in transmission mechanism for sewing machines, Serial No. 679,063, filed December 7, 1923; and application for improvement in needle mechanism, Serial No. 72,427, filed December 1, 1925.

I claim as my invention:

1. In a sewing machine, the combination of a rotary shaft, stitch forming mechanism operated thereby, stop clutch mechanism for starting and stopping said shaft and including a shiftable stop lever, a presser foot, a presser foot lifting lever, a power transmitter for transmitting power to said shaft and including clutch means, treadle means for operating said clutch means and said lifting lever, and having a lost motion connection with said stop lever for operating the latter subsequent to the operation of said clutch means and said lifting lever.

2. In a sewing machine, the combination of a rotary shaft, stitch forming mechanism operated thereby, stop clutch mechanism for starting and stopping said shaft and including a horizontally located pivotally supported shiftable stop lever having a pivoted spring pressed stop finger, a spring for normally urging the stop lever and its finger into its clutch-engaging position, a presser

foot, a presser foot lifting lever, a power transmitter for transmitting power to said shaft and including clutch means, treadle-operated means for operating said clutch means and presser foot lifting lever and having a lost-motion connection with said stop lever for operating the latter independently of said lifting lever, and means located in all positions thereof in juxtaposition to the clutch means of the power transmitter for adjusting said clutch means to vary the speed at which said rotary shaft starts to rotate.

3. In a sewing machine, the combination of a rotary shaft, a driving wheel carried thereby, stitch-forming mechanism, clutch means for connecting said wheel to the shaft, stop mechanism for controlling said clutch means and including a horizontally located pivotally supported shiftable stop lever having a pivoted spring pressed stop finger, a spring for normally urging the stop lever and its finger into its clutch-engaging position, a power transmitter comprising a power driven wheel having a driving connection with said driving wheel, clutch mechanism for connecting said driven wheel with a source of power, treadle-operated means for operating said clutch mechanism, and means located in all positions thereof in juxtaposition to the clutch mechanism of the power transmitter for adjusting said clutch mechanism to vary the speed at which said shaft starts to rotate.

4. In a sewing machine, the combination of a rotary shaft, stopping and starting mechanism therefor and including a swinging stop lever, a stop carried by said lever, brake means for said shaft, a swinging brake lever for releasing said brake means, means carried by said stop lever for operating said brake lever upon swinging the stop lever, said brake lever having means for permitting said stop lever means to move relatively to the brake lever while holding the brake lever in a fixed position of release.

5. In a sewing machine, the combination of a rotary shaft, stopping and starting mechanism therefor and including a swinging stop lever pivotally supported at one end, a stop carried by said lever at the opposite end, brake means for said shaft, a swinging brake lever for releasing said brake means, means carried by said stop lever between said stop and the pivot of said stop lever for operating said brake lever upon swinging the stop lever, said brake lever having means for permitting said stop lever means to move relatively to the brake lever while holding the brake lever in a fixed position of release.

6. In a sewing machine, the combination of a rotary shaft, stopping and starting mechanism therefor and including a swinging stop lever, a stop carried by said lever,

- brake means for said shaft, a swinging brake lever for releasing said brake means, means carried by said stop lever for operating said brake lever upon swinging the stop lever 5 and including means for permitting said last means to move relatively to said brake lever and to hold the same in a fixed position of release, a presser foot lifting lever, a rod for shifting said lifting lever and having a lost motion connection with said stop lever whereby said rod is operative to shift the lifting lever prior to the stop lever.
7. In a sewing machine, the combination of a rotary shaft, stopping and starting mechanism therefor and including a swinging stop lever, a stop carried by said lever, brake means for said shaft, a swinging brake lever for releasing said brake means, means carried by said stop lever for operating said 10 brake lever upon swinging the stop lever and including means for permitting said last means to move relatively to said brake lever and to hold the same in a fixed position of release, a presser foot lifting lever, a thread 15 pull-off lever connected to said lifting lever and operated thereby, a rod for shifting said lifting lever and having a lost motion connection with said stop lever whereby said rod is operative to shift the lifting lever 20 prior to the stop lever.
8. In a sewing machine, the combination of a presser foot, a presser foot lifting lever, a thread pull-off actuating lever, a rotary shaft having stop mechanism including a 25 shiftable stop lever, a drive shaft having stop mechanism controlled by said stop lever, a shiftable rod for operating all of said levers and having means whereby said rod is operative to shift said lifting lever prior 30 to said stop lever.
9. In a sewing machine, the combination of a presser foot, a presser foot lifting lever, a thread pull-off actuating lever connected to said lifting lever and operated thereby, a rotary shaft having stop mechanism including a shiftable stop lever, a drive shaft having stop mechanism controlled by said 35 stop lever, a shiftable rod for operating all of said levers and having means whereby said rod is operative to shift said lifting lever prior 40 to said stop lever.
10. In a sewing machine, the combination of a presser foot, a presser foot lifting lever, a shiftable thread pull-off member, a drive shaft, stopping and starting mechanism therefor, a shiftable rod for operating said 45 mechanism and having means movable into position and operative to shift the lifting lever and pull-off member prior to operating said stopping and starting mechanism.
11. In a sewing machine, the combination of stitching mechanism, a thread guide for guiding thread thereto, a presser foot, a presser foot lifting lever, a thread pull-off 50
- lever, a sliding rod having its upper end in 65 position to engage said lifting lever, a treadle connected to said rod, and means for operating said pull-off lever from said lifting lever.
12. In a sewing machine, the combination of stitching mechanism, a thread guide for 70 guiding thread thereto, a rotary shaft, stop mechanism for said shaft and including a stop lever, a presser foot, a presser foot lifting lever, a thread pull-off member, a sliding rod connected to said stop lever, and having its upper end extended into position 75 to engage said lifting lever for operating the same, and means for operating said thread-pull-off member from said rod.
13. In a sewing machine, the combination of stitching mechanism, a rotary drive shaft 80 connected therewith for operating the same, said shaft having a pair of clutch mechanisms, power driven means connected with one of said clutch mechanisms for rotating the shaft at speed, a hand wheel connected with the other clutch mechanism, and means for disconnecting the hand wheel clutch mechanism upon the rotation of the shaft by said power driven means thereby to permit the shaft to be driven by said power driven means without the rotation of the hand wheel.
14. In a sewing machine, the combination of stitching mechanism, a rotary drive shaft 85 connected therewith for operating the same, said shaft having a pair of clutch mechanisms, means for starting and stopping said rotary drive shaft, power driven means connected with one of said clutch mechanisms 90 for rotating the rotary drive shaft at speed, a hand wheel connected with the other clutch mechanism, and means for disconnecting the hand wheel clutch mechanism upon the rotation of the drive shaft by said power driven means thereby to permit the rotary drive shaft to be driven by said power driven means without the rotation of the hand wheel and the starting and stopping 95 of said rotary drive shaft free from the added weight or momentum of the hand wheel.
15. In a sewing machine, the combination of stitching mechanism, a rotary drive shaft 100 connected therewith for operating the same, said shaft having a pair of clutch mechanisms, means for starting and stopping said rotary drive shaft, power driven means connected with one of said clutch mechanisms 105 for rotating the rotary drive shaft at speed, a detachable hand wheel connected with the other clutch mechanism, and means for disconnecting the hand wheel clutch mechanism upon the rotation of the drive shaft by said power driven means thereby to permit the rotary drive shaft to be driven by said power driven means without the rotation of the hand wheel and the starting and stopping 110 of said rotary drive shaft.

of said rotary drive shaft free from the added weight or momentum of the hand wheel.

16. In a sewing machine, the combination of stitching mechanism, a drive shaft for operating the same, a power transmitter comprising clutch means for connecting and disconnecting the shaft from a source of power, a rock shaft, a pair of overlapping levers mounted on said rock shaft for controlling the operation of said clutch means, and means for adjusting said levers one relatively to the other to vary the speed at which said drive shaft starts to rotate and comprising a rotatable device passing through one of said levers with an end in position to contact with the other lever for regulating the movement of said last lever.

17. In a sewing machine, the combination of a rotary shaft, stitching mechanism operated thereby, means for starting and stopping said shaft and comprising a swinging stop lever, a brake for said shaft, a brake lever for said brake, means for operating said stop lever, and cooperating parts carried by said stop lever and brake lever for shifting the brake during the movement of the stop lever, one of the cooperating parts of one of said levers having an angularly projecting portion extending transversely to the brake lever and having an arc-shaped working face cooperating with a part of the other lever whereby the stop lever may be shifted a certain distance without releasing the brake.

18. In a sewing machine, the combination of a drive shaft, a machine arm, stitching mechanism connected to said shaft and carried by said arm, stop means for said shaft, a presser foot, presser foot lifting means, thread pull-off means, and a shiftable member for operating all of said means, said member having means for operating said stop means independently of said presser foot and thread pull-off means.

19. In a sewing machine, the combination of a rotary drive shaft, clutch mechanism for stopping and starting said shaft, presser foot mechanism, thread pull-off mechanism, and a common means for operating all of said mechanisms, said common means also adapted to operate one of said mechanisms independently of the others.

20. In a sewing machine, the combination of a rotary drive shaft, clutch mechanism for stopping and starting said shaft, presser foot mechanism, brake mechanism for said shaft, thread pull-off mechanism, and a common means for operating all of said mechanisms, said common means also adapted to operate one of said mechanisms independently of the others.

21. In a sewing machine, the combination of a drive shaft, stop motion control means for said shaft comprising a movable

stop lever and a stop carried thereby, presser foot mechanism, thread pull-off mechanism, and a common treadle controlled means coacting with said stop lever for operating all of said mechanisms, said common means also adapted to operate one of said mechanisms independently of the others.

22. In a sewing machine, the combination of a rotary shaft, stitching mechanism operated thereby, means for starting and stopping said shaft and comprising a swinging stop lever, a brake for said shaft, a brake lever for said brake, means for operating said stop lever, and cooperating parts carried by said stop lever and brake lever for shifting the brake during the movement of the stop lever, both of the cooperating parts of said levers having curved working faces, one of convex form and the other of concave form and cooperating with each other whereby the stop lever may be shifted a certain distance without releasing the brake.

23. In a sewing machine, the combination of a rotary drive shaft, clutch mechanism for starting and stopping said shaft, presser foot mechanism, thread pull-off mechanism, and a common means for operating all of said mechanisms, said common means also adapted to operate said starting and stopping clutch mechanism without operating the other mechanisms.

24. In a sewing machine, the combination of a rotary drive shaft, clutch mechanism for starting and stopping said shaft, presser foot mechanism, thread pull-off mechanism, and a common means for operating all of said mechanisms, said common means also adapted to operate said presser foot and thread pull-off mechanisms without operating the stopping and starting clutch mechanism.

25. In a sewing machine having an upright trunk provided with an overhanging arm, the combination of a rotary drive shaft, means for transmitting power to said shaft and including a pair of clutch members, a treadle for controlling the operation of said clutch members, starting and stopping mechanism for said shaft and including a pivotally supported shiftable stop lever located within and transversely of said upright trunk and having a spring pressed finger, a spring for normally urging the stop lever and its finger into stopping position, presser foot mechanism, a common means for operating said mechanisms and operative to operate either of said mechanisms independently of the other, and means for regulating the speed at which said shaft starts to rotate and located in juxtaposition to said clutch mechanism.

26. In a sewing machine having an upright trunk provided with an overhanging arm, the combination of a rotary drive shaft, means for driving the same, starting and

stopping mechanism for said shaft and including a pivotally supported shiftable stop lever located within and transversely of said trunk and having a spring pressed stop finger, a spring for normally urging the stop lever and its finger into its stopping position, presser foot mechanism, and a common means for operating said mechanisms and operative to operate either of said mechanisms independently of the other and including a shiftable rod having a lost-motion connection with the stop lever.

27. In a sewing machine having an upright trunk provided with an overhanging arm, the combination of a rotary shaft, stitch forming mechanism, a presser foot, a shiftable operating lever for said presser foot, stop mechanism for the shaft including a pivotally supported shiftable stop lever located within and transversely of said upright trunk and having a spring pressed stop finger, a spring for normally urging the stop lever and its finger into its stopping position, a rod for shifting said stop lever and operating lever, and means for connecting said rod to the stop lever to permit said rod to operate the stop lever either prior to or subsequent to the operation of said operating lever.

30. 28. In a sewing machine having an upright trunk provided with an overhanging arm, the combination of a rotary drive shaft, mechanism for starting and stopping said shaft and including a pivotally supported shiftable stop lever located within and transversely of said upright trunk and having a spring pressed stop finger, a spring for normally urging the stop lever and its finger into its stopping position, a presser foot lifting lever, and a shiftable rod for operating both of said levers and having a connection with said stop lever to permit independent operation of said lifting lever without operating the stop lever.

45. 29. In a sewing machine, the combination of a rotary drive shaft, mechanism for stopping and starting said shaft and including a shiftable stop lever, a presser foot lifting lever, a thread pull-off lever operated by said lifting lever, and a shiftable rod for operating said stop lever and lifting lever and having a connection with said stop lever to permit independent operation of said lifting lever without operating the stop lever.

55. 30. In a sewing machine, the combination of a rotary shaft, stitch forming mechanism operated thereby, means for starting and stopping said shaft, means for transmitting power to said shaft and including a pair of clutch members, a treadle for controlling the operation of said clutch members, and means including a pair of levers, one having a cam face cooperating with one of said clutch members and operative to vary the speed at which said rotary shaft starts to

rotate and an adjusting screw carried by one lever and engaging the other.

31. In a sewing machine, the combination of a rotary shaft, stitching mechanism operated thereby, means for starting and stopping said shaft and comprising a pivoted stop lever, a brake for said shaft, a brake lever for said brake, means for operating said stop lever, and cooperating parts carried by said stop lever and brake lever for shifting the brake during the movement of the stop lever, the cooperating part of the brake lever having an arc-shaped working face of which the pivotal point of the stop lever forms the center whereby the cooperating part of the stop lever may be shifted a certain distance without releasing the brake.

32. In a sewing machine, the combination of stitching mechanism, a rotary drive shaft connected therewith for operating the same, said shaft having a pair of clutch mechanisms, means for starting and stopping said rotary drive shaft, power driven means connected with one of said clutch mechanisms for rotating the rotary drive shaft at speed, a hand wheel connected with the other clutch mechanism, and spring-acting means for disconnecting the hand wheel clutch mechanism upon the rotation of the drive shaft by said power driven means thereby to permit the rotary drive shaft to be driven by said power driven means without the rotation of the hand wheel and the starting and stopping of said rotary drive shaft free from the added weight or momentum of the hand wheel.

33. In a sewing machine having an overhanging arm and a tubular work arm, a shaft carried by each of said arms, cooperating stitch forming means operated by said shafts, a rotary drive shaft located between and connected with said shafts, said rotary drive shaft having a pair of clutch mechanisms, means for starting and stopping said rotary drive shaft, power driven means connected with one of said clutch mechanisms for rotating the rotary drive shaft at speed, a hand wheel connected with the other clutch mechanism, and means for disconnecting the hand wheel clutch mechanism upon the rotation of the drive shaft by said power driven means thereby to permit the rotary drive shaft to be driven by said power driven means without the rotation of the hand wheel and the starting and stopping of said rotary drive shaft free from the added weight or momentum of the hand wheel.

34. In a sewing machine having an overhanging arm and a tubular work arm, a shaft carried by each of said arms, cooperating stitch forming means operated by said shafts, a rotary crank-formed drive shaft located between and transversely to and connected with said shafts for operating the same, said drive shaft having a pair of clutch mechanisms, means for starting and

stopping said rotary drive shaft, power driven means connected with one of said clutch mechanisms for rotating the rotary drive shaft at speed, a hand wheel connected 5 with the other clutch mechanism, and means for disconnecting the hand wheel clutch mechanism upon the rotation of the drive shaft by said power driven means thereby to permit the rotary drive shaft to be driven 10 by said power driven means without the rotation of the hand wheel and the starting and stopping of said rotary drive shaft free from the added weight or momentum of the hand wheel.

35. In a sewing machine, the combination of stitching mechanism, a drive shaft for operating the same, a power transmitter comprising a pair of clutch members for connecting and disconnecting the shaft from a 20 source of power, a pair of levers supported in position for controlling the operation of said clutch members, one of said levers having a cam face in position to engage one of said clutch members, a treadle connected 25 with one of said levers, and an adjustable screw carried by one of said levers and engaging the other for shifting the cam faced lever relatively to its clutch member thereby to vary the speed at which said drive shaft 30 starts to rotate.

36. In a sewing machine having an upright trunk provided with an overhanging arm, the combination of a rotary drive shaft, starting and stopping mechanism therefor and including a pivotally supported shiftable stop lever located within and transversely of said upright trunk and having a spring pressed stop finger, a spring for normally urging the stop and its finger into its 40 stopping position, presser foot mechanism, and a common means for operating said mechanisms and operative to operate either of said mechanisms independently of the other.

45. In a sewing machine, the combination of a rotary drive shaft, starting and stopping mechanism therefor, presser foot mechanism, thread control mechanism, and a common means for operating said mechanisms and operative to operate said starting and stopping mechanism independently of the other mechanisms or to operate said presser foot and thread control mechanisms independently of said starting and stopping 55 mechanism.

38. In a sewing machine, the combination of a rotary drive shaft, starting and stopping mechanism therefor, presser foot mechanism, thread control mechanism, and a common means for operating said mechanisms and operative to operate said starting and stopping mechanism independently of the other mechanisms or to operate said presser foot and thread control mechanisms independently of said starting and stopping 60 mechanism.

65

mechanism or to operate all of said mechanisms substantially simultaneously.

39. In a sewing machine, the combination of stitching mechanism, a rotary drive shaft connected therewith for operating the same, 70 said shaft having a starting and stopping clutch mechanism and a hand wheel clutch mechanism, a power transmitter mechanism also having clutch mechanism and connected with the starting and stopping clutch mechanism of the drive shaft for operating the same, and means for controlling the power transmitter clutch mechanism.

40. In a sewing machine, the combination of stitching mechanism, a rotary drive shaft connected therewith for operating the same, said shaft having a starting and stopping clutch mechanism and a hand wheel clutch mechanism, a power transmitter mechanism also having clutch mechanism and connected with the starting and stopping clutch mechanism of the drive shaft for operating the same, means for controlling the power transmitter clutch mechanism, and means for disconnecting the hand wheel clutch mechanism upon the rotation of the shaft by said power transmitter mechanism.

41. In a sewing machine, the combination of stitching mechanism, a rotary drive shaft connected therewith for operating the same, 95 said shaft having a starting and stopping clutch mechanism and a hand wheel clutch mechanism, a power transmitter mechanism also having clutch mechanism and connected with the starting and stopping clutch mechanism of the drive shaft for operating the same, a treadle operated means for controlling the operation of the power transmitter clutch mechanism, and means located in juxtaposition to the power transmitter clutch mechanism for regulating the speed of said shaft.

42. In a sewing machine, the combination of stitching mechanism, a rotary drive shaft connected therewith for operating the same, 110 said shaft having a starting and stopping clutch mechanism and a hand wheel clutch mechanism, a power transmitter mechanism also having clutch mechanism and connected with the starting and stopping clutch mechanism of the drive shaft for operating the same, means for controlling the power transmitter clutch mechanism, means for disconnecting the hand wheel clutch mechanism, 115 means located in juxtaposition to the power transmitter clutch mechanism for regulating the speed of said shaft.

Signed at Nyack, New York, this 20th day of June, 1921.

JOHN P. WEIS.
